RAILWAY SWITCH OPERATING APPARATUS

Herbert L. Bone, Swissvale, Pa., assignor to The Union Switch & Signal Company, Swissvale, Pa., a corporation of Pennsylvania

Application April 13, 1933, Serial No. 665,914

48 Claims. (Cl. 246—253)

My invention relates to railway switch operating apparatus, and particularly to apparatus of the type involving a longitudinally movable slide bar coating with elements for causing operation of a railway switch.

One feature of my invention is the provision of a novel and improved friction lock device for preventing creeping of the slide bar from either of its extreme positions.

Another feature of my invention is the provision of a novel and improved circuit controller for detecting any failure of the switch points to occupy their proper positions relative to the fixed rails in either extreme position of the switch.

A further feature of my invention is the provision of a novel and improved latching device which may be incorporated into the circuit controller when desired, and which when utilized, provides means whereby, if the indication contacts of the circuit controller are improperly forced open, as by a train trailing the switch, when the switch points are locked in either of their extreme positions, these contacts will be positively held open by the latching device until the latching device is manually operated to release the contacts.

I will describe several forms of apparatus embodying my invention, and will then point out the novel features thereof in claims.

In the accompanying drawings, Fig. 1 is a top plan view showing a railway switch A actuated by one form of switch operating mechanism B embodying my invention. Fig. 2 is an enlarged top plan view of a portion of the mechanism shown in Fig. 1, with the top plate 18 and circuit controller C removed to better illustrate the construction. Fig. 3 is a front view of a portion of the mechanism shown in Fig. 2. Fig. 4 is an enlarged top plan view of the circuit controller C forming part of the mechanism shown in Fig. 1, the cover 30 being removed to better illustrate the construction of the circuit controller.

Figs. 5 and 6 are sectional views taken substantially on the lines V—V and VI—VI, respectively, of Fig. 4. Fig. 7 is a view, partly in plan, and partly in section of the contact drum 39^a forming part of the circuit controller C illustrated in Figs. 4, 5 and 6, the contact drum being rotated to the position in which all of the contact members secured thereto are exposed to view. Fig. 8 is a front elevational view of the pin 60^a which connects the crank arm 62^a of the circuit controller C with the rack bar 57^a. Fig. 9 is an enlarged sectional view taken on the line IX—IX of Fig. 2, and Fig. 10 is a sectional view taken on the

line X—X of Fig. 9. Fig. 11 is an enlarged fragmentary bottom view of the crank arm 64^a forming part of the circuit controller shown in Figs. 4, 5 and 6. Fig. 12 is an enlarged top plan view of the bolt 66^a for fastening the roller 65^a of the circuit controller C to the crank arm 64^a. Figs. 13 and 14 are top plan and side views, respectively, of a latch head 103 forming part of the latching mechanism associated with the circuit controller C, and also embodying my invention. Fig. 15 is a top plan view with cover removed of the circuit controller C showing the parts in the positions which they occupy when it is desired to have the point adjacent the switch movement in a left-hand layout normally open instead of normally closed, as shown in Fig. 1. Fig. 16 is a fragmentary top plan view showing a switch operating mechanism B applied to a right-hand switch layout. Fig. 17 is a top plan view showing a movable point frog A¹ operated by a switch operating mechanism B¹ embodying my invention. Fig. 18 is a side view of the switch operating mechanism shown in Fig. 17 with some of the parts removed to better illustrate the construction. Fig. 19 is a top plan view of a circuit controller C¹ forming part of the mechanism B¹, and also embodying my invention, a portion of the cover for this circuit controller being removed to better illustrate the construction. Fig. 20 is a sectional view taken on the line XX—XX of Fig. 19.

Similar reference characters refer to similar parts in each of the several views.

Referring first to Fig. 1, the reference character A designates a railway switch comprising as usual two fixed rails 1 and 1^a and two movable switch points 2 and 2^a. The fixed rails 1 and 1^a are laid on tie plates 3 and are secured to cross-ties 4 in the usual manner. The switch points 2 and 2^a are connected together by a front rod 5, a head rod 6, and a tie rod 6^a, and may be moved into a normal or reverse position by means of a switch operating mechanism B which is connected with the head rod 6 through the medium of an operating rod 7 and the usual switch basket 8. When the switch occupies its normal position, in which position it is shown in Fig. 1, the switch point 2 engages the fixed rail 1, and the switch point 2^a is spaced a predetermined distance from the fixed rail 1^a. When the switch is reversed, however, the switch point 2^a then engages the fixed rail 1^a and the switch point 2 is spaced from the fixed rail 1.

The switch operating mechanism B is mounted on a bed plate 9 which is secured to the ties 4 ad-

jaçent the outer side of the rail 1, and in the form here shown, this mechanism comprises a base plate 10 (see Figs. 2 and 3), bolted to the bed plate 9, and carrying a longitudinally movable slide bar 11 which is guided between rollers journaled on studs which project upwardly from the base plate. The slide bar 11 is adapted to be reciprocated between two extreme positions, and for this purpose the slide bar is operatively connected 5 with the piston rod 12 of a fluid pressure motor 13 which is bolted to the base plate 10. As shown in the drawings, the slide bar is connected with the piston rod 12 at the left-hand end of the slide bar, but it should be pointed out that in actual practice the slide bar will usually be so constructed 10 and the parts will be so arranged that the slide bar can be connected with the piston rod of the motor 13 at whichever end of the slide bar proves to be the most convenient for any particular 15 installation, and the bed plate 9 will usually be drilled in such manner that the motor can be bolted to the bed plate at either end of the slide bar.

As best seen in Fig. 3, the slide bar 11 consists 20 of an upper bar 11^a and a lower bar 11^b riveted together in superposed parallel spaced relation. A roller 15 is rotatably mounted between the bars 11^a and 11^b, and this roller coacts with an alligator jaw 16 which is journaled at its lower end 25 in the base plate 10 and at its upper end in a top plate 18. The top plate 18 is bolted to the base plate 10 in parallel spaced relation and serves 30 to prevent vertical displacement of the slide bar 11 between its roller guides. The alligator jaw 16 is operatively connected with the previously 35 described operating rod 7 in the usual and well known manner.

In addition to carrying the roller 15, the slide bar 11 carries two locking dogs 19 and 20 which 40 are attached to the upper and lower bars 11^a and 11^b, respectively, and which cooperate with suitable notches 19^a and 20^a, respectively, formed in an adjustable lock rod L. The lock rod L is of 45 the usual and well-known construction, and is connected to the front rod 5 of the switch A in the usual manner. The parts which have thus far been described are in widespread use, and their operation is well understood, so that for purposes of the present disclosure, it is believed that the 50 following brief description of the operation of these parts will be sufficient.

When the slide bar 11 occupies its extreme normal position, in which position it is shown in the drawings, the switch points are held in their 55 normal positions by engagement of the roller 15 with the right-hand side of the alligator jaw 16, and under these conditions, the locking dog 19 enters the notch 19^a in the lock rod L and locks the switch points in their normal positions. 60 When, however, the slide bar is moved from its extreme normal position to its extreme reverse position, the first part of the movement of the slide bar withdraws the locking dog 19 from the notch 19^a in the lock rod L to unlock the 65 switch, the intermediate part of the movement of the slide bar causes the switch points to be moved to the extreme position opposite to that in which they are shown in Fig. 1, and the final part of the movement of the slide bar moves the locking dog 20 into engagement with the notch 20^a in the lock rod L to lock the switch points in their 70 reverse positions. The operation of the apparatus when the slide bar is subsequently restored to its extreme normal position is exactly the 75

reverse of that just described and will be obvious from an inspection of the drawings.

It has been found that under some conditions there is a tendency for the slide bar 11 to creep 5 away from the extreme position which it occupies when the switch operating mechanism is at rest, this tendency probably being due to vibration caused by passing trains. When such creepage occurs, it is manifest by the fact that the signals which govern traffic over the switch can- 10 not be cleared because of the control of these signals by an indication circuit controller C which is controlled in part by the slide bar, and which I will describe in detail hereinafter. It is obvious, therefore, that this creepage of the slide 15 bar is undesirable, and one of the objects of my invention is to provide a friction lock which prevents this creepage, my friction lock being an improvement over that shown and described in Letters Patent of the United States No. 1,732,957, 20 granted to Charles Thorn and William C. McWhirter, on October 22, 1929, for Railway switch operating mechanism.

Referring now again to Figs. 2 and 3, my improved friction lock is disposed on the side of the 25 slide bar 11 opposite to the alligator jaws 16 and in transverse alignment with the alligator jaw, and in the form here shown, this lock comprises a curved dog 21 secured intermediate its ends to a pin 22 which is journaled in the base 30 plate 10 and top plate 18, and a curved dog 23 which is mounted to rotate at one end on the pin 22, the dog 23 being provided with bifurcations which straddle the right-hand end of the dog 21, as shown in Fig. 3. Formed on the inner side of 35 the dog 23 directly opposite, and in alignment with, a tapped hole 24 which is provided in the right-hand end of the dog 21 is a socket 25; and interposed between the socket 25 and an adjustable plug 26 which is screwed into the outer 40 end of the hole 24, is a compressed coil spring 27 which biases the dogs 21 and 23 to the positions in which the inner ends of these dogs extend part way into the path of movement of the roller 15, the dogs being stopped in the desired 45 positions by means of stop pins 28 extending upwardly from the base plate 10. The parts are so proportioned that when the slide bar 11 is in its extreme normal position in which it is shown in the drawings, the end surface 23^a of the dog 23 will be very close to the lower left-hand side of the roller 15, as viewed in Fig. 2, and that, when the slide bar occupies its opposite or reverse 50 extreme position, the end surface 21^b of the dog 21 will be located very close to the lower right-hand side of the roller 15. Furthermore, the end surface of both of these dogs is disposed at an acute angle to the path of movement of the roller 15, as will be apparent from an inspection 55 of Fig. 2. It will be seen, therefore, that when the slide bar 11 occupies its extreme normal position, it cannot move out of this position unless sufficient force is exerted on it to force dog 23 back against the opposing force of spring 27 a 60 sufficient amount to permit roller 15 to clear the end surface 23^a of dog 23, and that, when the slide bar 11 occupies its extreme reverse position, it cannot move out of this position unless sufficient force is exerted on it to cause dog 21 to 65 be forced back against the opposing force of spring 27 a sufficient distance to permit roller 15 to clear the end surface 21^b of the dog 21. The amount of compression of spring 27 will usually be so adjusted that the force required to move 70 75 80 85 90 95 98 99 100

the dogs out of the path of movement of the roller 15 will be greater than any force tending to cause the slide bar to creep, but will not be enough to interfere with the movement of the 5 slide bar by the motor. In this connection, it should be pointed out that the necessary operation of the friction lock by the motor takes place during the unlocking and locking portions of the stroke of the slide bar, and the load on 10 the motor at this time is much less than it is during that portion of the stroke of the slide bar in which the reversal of the switch points occurs, so that the force available to operate the lock is more than ample. Furthermore, 15 when the slide bar is being moved to an extreme or locking position after reversal of the switch points, the roller 15 then cooperates with a side surface 21^c on the dog 21, or a side surface 23^b on the dog 23 as the case may be, and not with 20 the end surface of these dogs; and the side surfaces 21^c and 23^b are disposed at such angles with respect to the path of movement of the roller that the force which the slide bar must exert when the roller is engaging one of these 25 surfaces, in order to move the associated dog out of the path of movement of the roller, is considerably less than that required to move such dog out of the path of movement of the roller when the slide bar is being moved away from 30 an extreme position.

The indication circuit controller C referred to hereinbefore is supported and enclosed in a suitable casing 29 (see Figs. 4, 5 and 6) which is bolted to the right-hand end of the base plate 35 10, the parts being so constructed and so designed that this circuit controller can be readily removed as a unit from the portion of the switch 35 operating mechanism described hereinbefore without in any way disturbing this portion of the mechanism, as will be apparent from an inspection of Figs. 2 and 4. The interior of the casing 29 is divided by means of a partition 32 into two compartments 33 and 34, both of which compartments are closed at their upper ends by 40 a single removable cover 30. The compartment 33 is relatively shallow and is provided with a bottom wall 35 which is disposed wholly above the slide bar 11. The compartment 34, however, 45 is relatively deep and communicates at its lower end with a recess 31 formed in the top of the base plate 10. Extending into the compartment 33 are two tubular openings 36 through which electrical conductors may be brought into this compartment.

55 A frame 38 is secured to the bottom wall 35 of the left-hand compartment 33, and journaled end to end in suitable bearings formed in this frame are two contact drums 39^a and 39^b. Mounted on an insulating portion of the contact 60 drum 39^a are five contact members 40^a, 41^a, 42^a, 43^a and 44^a (see Fig. 7) which cooperate, in a manner to be described hereinafter, with a plurality of fixed contact fingers 45^a, 46^a, 47^a, 48^a, 49^a and 50^a, and mounted on an insulating portion of the contact drum 39^b are five contact members 40^b, 41^b, 42^b, 43^b and 44^b which cooperate, with a plurality of fixed contact fingers 45^b, 46^b, 47^b, 48^b, 49^b and 50^b in the same manner that the 65 contact members 40^a, 41^a, 42^a, 43^a and 44^a cooperate with the fixed contact fingers 45^a, 46^a, 47^a, 48^a, 49^a and 50^a. The contact fingers 45^a, 46^a, 47^a, 45^b, 46^b, and 47^b are each fastened to a molded insulating member 51 which is bolted to the frame 70 75 38 on the left-hand side of the two contact drums

39^a and 39^b, as viewed in Fig. 4, while the fingers 48^a, 49^a, 50^a, 48^b, 49^b, and 50^b, are each fastened to a molded insulating member 52 similar to the molded insulating member 51, the insulating member 52 being bolted to the frame 38 on the right-hand side of the contact drums 39^a and 39^b, as viewed in Fig. 4. A block 53 of electrical conducting material (see Fig. 5) is clamped against the upper side of the lower end of each contact finger by means of the same screw which fastens such finger to the associated insulating member, and each contact block 53 is provided with an integral raised portion 53^a having a threaded hole which receives a terminal screw 54, thus providing a convenient means for connecting electrical conductors with the contact fingers.

The contact drums 39^a and 39^b are each adapted to be rotated between an intermediate and two extreme positions in a manner which I will describe hereinafter, and as shown in the drawings, the contact drum 39^a is rotated in a clockwise direction, as viewed from the bottom in Fig. 4, to its normal extreme position, while the contact drum 39^b is rotated in a counter-clockwise direction, as viewed from the bottom in Fig. 4 to its normal extreme position. The parts are so proportioned that when the contact drums occupy their normal extreme positions, the contact member 40^a will engage the fixed contact fingers 45^a 30 and 48^a to close a contact 45^a—40^a—48^a, and the contact member 41^a will engage the fixed contact fingers 46^a and 49^a to close a contact 46^a—41^a—49^a, while the contact member 42^b will engage the fixed contact fingers 47^b and 50^b to 35 close a contact 47^b—42^b—50^b and the contact member 44^b will engage the contact fingers 48^b and 49^b to close a contact 48^b—44^b—49^b. If, now, the contact drum 39^a is rotated in a counter-clockwise direction, as viewed from the bottom in 40 Fig. 4, from its normal extreme position to its intermediate position, and the contact drum 39^b is simultaneously rotated in a clockwise direction, as viewed from the bottom in Fig. 4, from its normal extreme position to its intermediate position, contact member 42^a will first move into engagement with contact finger 47^a to complete a contact 47^a—42^a—50^a, then the contact members 40^a and 41^a will simultaneously move out of engagement with the contact fingers 48^a and 49^a, 45 respectively, to open the contacts 45^a—40^a—48^a and 46^a—41^a—49^a, then contact member 44^b will move out of engagement with the contact fingers 48^b and 49^b to open the contact 48^b—44^b—49^b, and finally, the contact members 43^a and 43^b will simultaneously move into engagement 50 with the contact fingers 48^a, 49^a and 48^b, 49^b, respectively, to close contacts 45^a—43^a—49^a and 48^b—43^b—49^b. Furthermore, if the contact drums 55 39^a and 39^b are simultaneously rotated in opposite directions from their intermediate positions to what I shall term their "reverse" extreme positions, contact members 43^a and 43^b will first simultaneously move out of engagement with the contact fingers 48^a, 49^a and 48^b, 49^b, respectively, to open the contacts 48^a—43^a—49^a and 48^b—43^b—49^b, then contact members 40^b and 41^b will simultaneously move into engagement 60 with the fingers 48^b and 49^b, respectively, to close contacts 45^b—40^b—48^b and 46^b—41^b—49^b, then contact member 44^a will move into engagement with contact fingers 48^a and 49^a to close a contact 48^a—44^a—49^a, and finally contact member 42^b will move out of engagement with contact 65 70 75 75 75

finger 47^b to open contact 47^b—42^b—50^b. During simultaneous rotation of the contact drums in opposite directions from their reverse extreme positions to their intermediate extreme positions, and 5 from their intermediate extreme positions to their normal extreme positions, the operation of the various contacts will be exactly the reverse of that just described, and will therefore be readily understood from the foregoing and from an inspection of the drawings without further description. 10

A gear wheel 55^a is secured to one end of the contact drum 39^a, and this gear wheel meshes with rack teeth 56^a cut in one end of a rack bar 57^a. A 15 gear wheel 55^b, similar to the gear wheel 55^a, is likewise secured to one end of the contact drum 39^b, and this latter gear wheel meshes with rack teeth 56^b cut in one end of a rack bar 57^b. The two rack bars 57^a and 57^b are slidably mounted 20 side by side in the compartment 33 for reciprocation between two extreme positions, and the ends of these rack bars opposite to those in which the rack teeth are cut extend through the partition 32 into the compartment 34, and are provided 25 within the compartment 34 with flattened offset portions 58^a and 58^b, respectively, the offset portion 58^a being disposed above the plane of the associated rack bar 57^a and the offset portion 58^b being disposed below the plane of the associated 30 rack bar 57^b, as shown in Fig. 6, so that a considerable amount of clearance is provided between the rack bars at the offset portions. A transverse slot 59^a is cut in the offset portion 58^a, and a similar slot 59^b is cut in the offset portion 58^b, the two slots being so disposed that their open ends 35 face in opposite directions. The slot 59^a cooperates with a pin 60^a which is mounted at its ends in bifurcations 61^a (see Fig. 6) formed on one end of a crank arm 62^a, and the slot 59^b likewise cooperates with a pin 60^b which is mounted at its 40 ends in bifurcations 61^b formed on one end of a crank arm 62^b. The pins 60^a and 60^b are similar, and as best seen in Figs. 4 and 8, the pin 60^a is made round at its ends to permit it to rotate freely 45 in the bifurcations 61^a, but the portion of this pin which cooperates with the slot 59^a in the offset portion 58^a is made flat on two sides to provide a sliding fit with the slot 59^a. The end of the arm 62^a opposite to that in which the pin 60^a is 50 mounted is secured to the upper end of a vertical rockshaft 63^a (see Fig. 6), which rock shaft is journaled in the compartment 34 on one side of the slide bar 11; and the end of the arm 62^b opposite to that in which the pin 60^b is mounted 55 is secured to the upper end of a vertical rockshaft 63^b which is journaled in the compartment 34 on the side of the slide bar 11 opposite to that on which the rockshaft 63^a is journaled. It will be apparent, therefore, from the foregoing description and from an inspection of the drawings, that rotation of the rockshafts 63^a and 63^b will cause 60 longitudinal movement of the rack bars 57^a and 57^b which, in turn, will cause rotation of the contact drums 39^a and 39^b. 65

The two rockshafts 63^a and 63^b are operatively connected with the slide bar 11, to be oscillated thereby, in the following manner. Formed integral with the rockshaft 63^a directly below the arm 62^a is a crank arm 64^a, and formed integral 70 with the rockshaft 63^b directly below the crank arm 62^b is a crank arm 64^b. The crank arms 64^a and 64^b are of relatively wide web-like construction and each extends substantially parallel to the 75 slide bar 11. A roller 65^a is attached, by means of

a bolt 66^a and a nut 67^a, to the crank arm 64^a, and a roller 65^b, similar to the roller 65^a, is likewise attached, by means of a bolt 66^b and a nut 67^b, to the crank arm 64^b. The roller 65^a cooperates with two recesses *a*¹ and *a*², (see Fig. 2) formed 5 in one side edge of a motion plate 68 which is carried on top of, and driven by the slide bar 11, and the roller 65^b similarly cooperates with two recesses *b*¹ and *b*² formed in the side of the motion plate 68 opposite to that in which the recesses *a*¹ and *a*² are formed. A spring 69 is stretched 10 between two upstanding pins 70^a and 70^b provided on the arms 64^a and 64^b, respectively, and this spring constantly biases the rockshafts to such positions that the rollers 65^a and 65^b will 15 enter the associated recesses in the motion plate whenever these recesses are in alignment with the rollers, unless the rollers are prevented from doing so by point detector mechanism which I will describe hereinafter. 20

The recess *a*¹ in the motion plate 68 is relatively short and is so disposed that this recess will align with the roller 65^a when and only when the slide bar 11 occupies its extreme normal position in which it is shown in the drawings. The recess *a*² 25 joins the right-hand end of the recess *a*¹, as viewed in Fig. 2, and is of such length that this latter recess will align with the roller 65^a when the slide bar 11 occupies any position except its extreme normal or its extreme reverse position. 30 The recess *a*¹ is approximately twice as deep as the recess *a*², and it will be apparent, therefore, that when the roller 65^a enters the recess *a*¹, the rockshaft 63^a will be rotated, in a counter-clockwise direction, as viewed in Fig. 4, to one extreme position; that when the roller 65^a is forced out of 35 both recesses *a*¹ and *a*², the rockshaft 63^a will be rotated in a clockwise direction, as viewed in Fig. 4, to another extreme position; and that when the roller 65^a enters the recess *a*², the rockshaft 63^a 40 will be rotated to an intermediate position approximately midway between its two extreme positions. The recess *b*¹ is similar to the recess *a*¹, but is so disposed that this recess will align with the roller 65^b when and only when the slide bar 11 45 occupies its extreme reverse position. The recess *b*² is likewise similar to the recess *a*², and is so disposed that this recess will align with the roller 65^b when the slide bar occupies any position intermediate its two extreme positions. It follows that 50 the rockshaft 63^b will be rotated to one extreme position when the roller 65^b enters the recess *b*¹, to another extreme position when the roller 65^b is forced out of both recesses, and to an intermediate position approximately midway between 55 its two extreme positions when the roller 65^b enters the recess *b*². The recesses *a*¹, *a*², *b*¹ and *b*², in addition to being proportioned and disposed in the manner above described, are so designed 60 that any rotation of the rockshafts 63^a and 63^b due to engagement of the rollers 65^a and 65^b with these recesses will be equal and opposite.

As was pointed out hereinbefore, rotation of the rockshafts 63^a and 63^b causes corresponding rotation of the contact drums 39^a and 39^b, and 65 the parts are so proportioned that each of these contact drums will be rotated to its normal extreme position, its intermediate extreme position, or its reverse extreme position according as the associated rockshaft is rotated to the extreme 70 position in which it is shown in the drawings, its intermediate extreme position or the extreme position opposite to that in which it is shown in the drawings.

The motion plate 68 is driven by the slide 75

bar 11 through the medium of a bolt 72 (see Figs. 2, 3, 9 and 10) having a relatively large flat head, and having adjacent its head a rectangular shoulder 72^a which fits into a rectangular slot 73 provided in one end of the motion plate. The parts are so proportioned that endwise movement of the motion plate relative to the slide bar is prevented, but that, a limited amount of lateral motion of the motion plate relative to the slide bar is permitted. The motion plate is maintained in the desired lateral position relative to the circuit controller by means of a depending rib 74 (see Fig. 6) formed on the underside of the bottom wall 35 of the compartment 33, which rib extends into a longitudinally extending groove 75 (see Figs. 6 and 9) provided in the upper side of the motion plate.

Under certain conditions which will be described hereinafter, it is desirable to turn the motion plate over so that the side of the motion plate which is the lower side in the drawings will then become the upper side, and in order to permit this to be done, the lower side of the motion plate is provided with a longitudinally extending groove 25 76 (see Figs. 6 and 9) similar to the groove 75.

One advantage of fastening the motion plate to the slide bar in the manner just described is that while the slide bar may receive sudden thrusts from the operating rod 7 and lock rod L 30 as high speed trains pass over the switch points, these thrusts will not be transmitted to the motion plate, and will not, therefore, affect the operation of the circuit controller in any way. Another advantage of securing the motion plate to the slide bar in the manner previously described, is that it is an easy matter to turn the slide bar over when it is desired to do so.

In order to facilitate adjustment of the parts and to compensate for wear, it is desirable to be 40 able to readily vary the positions of the crank arms 62^a and 62^b relative to the associated rockshafts 63^a and 63^b, and I therefore secure these arms to the rockshafts by adjustable means which I will now describe. Referring to Fig. 6, and 45 particularly to the means for fastening the arms 62^a to the rockshaft 63^a, this means, in the form here shown, comprises a tap bolt 78 having an unthreaded shank portion adjacent its head, and a threaded portion at the end opposite to its head. The threaded portion is screwed into a 50 tapped hole 79^a provided in the upper end of the rockshaft 63^a, while the unthreaded shank portion extends downwardly with some clearance through an axial slot 80^a, provided in the end 55 of the crank arm 62^a opposite to that which is bifurcated. The means for fastening the crank arm 62^a to the rockshaft 63^a also comprises a stud bolt 81^a having a threaded portion at each end and an eccentric unthreaded portion intermediate 60 its ends. The threaded portion at one end of the bolt 81^a is screwed into a tapped hole 82^a provided in the crank arm 64^a while the eccentric portion of the bolt 81^a is disposed in a hole 83^a provided in the crank arm 62^a. A nut 84^a is screwed onto 65 the other threaded portion of the bolt 81^a, and when tightened, prevents the bolt from turning. Interposed on the bolt 78^a between the upper side of the crank arm 62^a and the head of the bolt, and also on the bolt 81^a between the upper side 70 of the crank arm 62^a and the nut 84^a, is a flat plate 86^a which serves to distribute the pressure exerted by the head of the bolt 78^a and the nut 84^a.

With the above described construction, it will 75 be seen that if the tap bolt 78^a is first un-

screwed a certain amount and the nut 84^a is backed off the stud bolt 81^a, and the stud bolt is then rotated by inserting a screw driver in a saw kerf 85^a provided in the upper end of this latter bolt, the position of the arm 62^a relative 5 to the rockshaft 63^a may be varied an amount which depends upon the proportioning of the parts. After adjustment has been made in this manner, the tap bolt 78^a and nut 84^a will, of course, again be tightened to lock the arm in its 10 new position.

The means for fastening the crank arm 62^b to the rockshaft 63^b is similar to the means described above for fastening the crank arm 62^a to the rockshaft 63^a, and the corresponding parts 15 are designated by the same reference characters with suitable distinguishing exponents. It is believed, therefore, that a detailed description of the means for fastening the crank arm 62^b to the rockshaft 63^b is unnecessary.

For the same reasons that it is desirable to be able to vary the positions of the crank arms 62^a and 62^b relative to the rockshafts 63^a and 63^b, it is also desirable to be able to vary the positions of the rollers 65^a and 65^b relative to the 25 associated crank arms 64^a and 64^b, and for this purpose, I preferably make the portion 87 of each bolt 66 (see the bolt 66^a shown in Fig. 12) which extends through the associated roller 65 eccentric to that portion 88 of the bolt which extends 30 through the associated arm 64, and I provide the upper side of the portion 87 of each bolt 66 with an upstanding pin 89 which is adapted to enter any one of a plurality of spaced holes 90 (see Fig. 11) provided in the underside of the 35 associated arm 64. With this construction, it will be seen that by backing off the nut 67 associated with either one of the bolts 66 far enough to permit the pin 89 on such bolt to be withdrawn from the hole 90 which it then occupies, turning 40 such bolt to the angular position in which the pin 89 enters a selected new hole, and again tightening the associated nut 67, the desired adjustment between either roller and the associated 45 crank arm may be quickly and conveniently made.

The circuit controller C also comprises point detector mechanism for controlling the rockshafts 63^a and 63^b in accordance with the positions of the switch points, independently of the control of these rockshafts by the slide bar 11. As 50 here shown, this mechanism comprises two additional crank arms 92^a and 92^b (see Figs. 4 and 6) which are secured to the lower ends of the rockshafts 63^a and 63^b, respectively, and which are provided at their outer ends with rollers 93^a and 55 93^b that cooperate with an annular recess 95 in a point detector rod D of the usual and well-known type. The point detector rod D is slidably mounted in suitable guides provided in the base plate 10 at the opposite sides of the recess 31 and 60 65 is adjustably secured in the usual manner to the normally closed point 2 of the switch A. The recess 95 is so designed, and the parts are so proportioned, that this recess will align with the roller 93^a when and only when the switch point 2 70 is tight against the stock rail 1, and with the roller 93^b when and only when the switch point 2^a is tight against the stock rail 1^a. The parts are also so proportioned that the roller 93^a will enter the recess 95 when and only when the roller 65^a 75 enters the recess a¹ in the motion plate 68, and that the roller 93^b will enter the recess 95 when and only when the roller 65^b enters the recess b¹ in the motion plate 68. The parts are further so proportioned that if either roller 93^a or 93^b is 75

forced out of the recess 95 due to the movement of the point detector rod D, the associated rock-shaft 63^a or 63^b will be rotated from the extreme position which it then occupies to its intermediate position.

The operation as a whole, of the portion of the circuit controller thus far described is as follows: As shown in the drawings, the slide bar 11 occupies its extreme normal position, and the switch points 2 and 2^a likewise occupy their extreme normal positions so that the switch point 2 is held tightly against the associated fixed rail 1. Under these conditions, both recesses b¹ and b² in the motion plate 68 are, of course, out of alignment with the roller 65^b on the crank arm 64^b attached to rockshaft 63^b, and the roller 65^b is therefore forced to ride up onto the outer edge of the motion plate so that the rockshaft 63^b is rotated to its one extreme position, thus causing the contact drum 39^b to be rotated to its normal extreme position. Furthermore, under these conditions, the recess a¹ in the motion plate 68 is in alignment with the roller 65^a on the crank arm 64^a attached to the rockshaft 63^a and the recess 95 in the point detector rod D is in alignment with the roller 93^a on the crank arm 92^b attached to rockshaft 63^a, and the rockshaft 63^a is therefore rotated by the spring 69 to the extreme position in which it is shown in the drawings, thus causing the contact drum 39^a to be rotated to its normal extreme position. As was previously pointed out, when the contact drums 39^a and 39^b occupy their normal extreme positions, contacts 45^a—40^a—48^a, 46^a—41^a—49^a, 47^b—42^b—50^b and 48^b—44^b—49^b are all closed, while all of the remaining contacts are open.

I will now assume that with the parts in the positions just described, the slide bar 11 is moved from its extreme normal position to its extreme reverse position to move the switch points from their normal position to their reverse position. During the first or unlocking part of this movement of the slide bar, no motion of the switch points takes place for the reasons pointed out hereinbefore, but during the initial part of the resultant movement of the motion plate 68, the roller 65^a is forced out of recess a¹ and into the recess a², and at the same time, recess b² moves into alignment with the roller 65^b. As a result, the rockshaft 63^a is rotated in a positive manner from the position shown to its intermediate position, and the rockshaft 63^b is simultaneously rotated, by virtue of the bias of the spring 69, from the position shown to its intermediate position. The rotation of the rockshafts 63^a and 63^b to their intermediate positions, of course, causes the contact drums 39^a and 39^b to rotate to their intermediate positions, and this latter rotation, in turn, causes contact 47^a—42^a—50^a to first become closed, then contacts 45^a—40^a—48^a and 46^a—41^a—49^a to become simultaneously opened, then contact 48^b—44^b—49^b to become opened, and finally contacts 48^a—43^a—49^a and 48^b—43^b—49^b to become simultaneously closed, as has been pointed out hereinbefore. The rotation of the rockshaft 63^a to its intermediate position also moves the roller 93^a on the crank arm 92^a out of the recess 95 in the point detector rod D, and it will be apparent, therefore, that during that portion of the movement of the slide bar which causes the shifting of the switch points, that is to say, during the intermediate part of the movement of the slide bar, both rollers 93^a and 93^b will be clear of the point detector rod, so that there is no actual engagement between the point detector rod and

the rollers 93^a and 93^b under these conditions. After the intermediate part of the movement of the slide bar 11 has been completed, and the final or locking part of the movement of the slide bar has been partly effected, recess a² moves out of alignment with roller 65^a, and recess b¹ simultaneously moves into alignment with roller 65^b. When this happens, rockshaft 63^a will, of course, be rotated in a positive manner from its intermediate position to the extreme position opposite to that in which it is shown in the drawings, thereby causing contact drum 39^a to be rotated to its reverse extreme position. Furthermore, if when the recess b² moves into alignment with the roller 65^b, the point 2^a is then tight against the fixed rail 1^a, so that the recess 95 is then in alignment with the roller 93^b, as will be the case if the parts are in proper adjustment and the points have not been damaged, spring 69 will rotate rockshaft 63^a from its intermediate position to the extreme position opposite to that in which it is shown in the drawings, thus rotating the contact drum 39^b to its reverse extreme position. As the contact drums move from their intermediate positions to their reverse extreme positions, contacts 48^a—43^a—49^a and 48^b—43^b—49^b first become simultaneously opened, then contacts 45^a—40^a—48^a and 46^b—41^b—49^b become simultaneously closed, then contact 48^a—44^a—49^a becomes closed, and finally contact 47^b—42^b—50^b becomes opened, as described hereinbefore.

When the slide bar is in its extreme reverse position and the switch points are in their full reverse positions, if the slide bar is then restored to its extreme normal position to restore the switch points to their normal positions, the operation of the apparatus will be exactly the reverse of that just described, and it is believed, therefore, that this operation will be apparent from the foregoing and from an inspection of the drawings without further description.

I will now assume that the parts are in the positions in which they are shown in the drawings, and that a train trails the switch. Under these conditions, while the train is trailing the switch, the switch points will be displaced a certain amount from their normal extreme positions by the wheels of the train, and this displacement will cause the point detector rod D to move upwardly as viewed in Figs. 1 and 4, an amount which depends upon the amount of displacement of the closed point, that is, the point 2. This upward movement of the point detector rod will cause the bevel face of the recess 95 in the point detector rod D to engage roller 93^a and will thus rotate rockshaft 63^a in a clockwise direction as viewed in Fig. 4. This rotation of the rockshaft 63^a, in turn, will move roller 65^a out of engagement with recess a¹ in the motion plate 68, will cause spring 69 to become extended, and will also cause contact drum 39^a to rotate from its normal extreme position toward its intermediate position, thereby causing contact 47^a—42^a—50^a to become closed, and contacts 45^a—40^a—48^a and 46^a—41^a—49^a to become opened, and if displacement of the closed point is sufficient to force the roller 93^a completely out of the recess 95, contact 48^a—43^a—49^a will become closed. When the train has completely trailed the switch, the displacing force on the points will, of course, be removed, and the points will then tend to spring back to their normal positions. The movement of the points toward their normal positions will move the point detector rod D downwardly as viewed in Figs. 1 and 4, and if the amount of

this movement is sufficient to permit the roller 93^a to fully reenter the recess 95, the spring 69 will restore the rockshaft 63^a to the position in which it is shown in the drawings, thereby restoring the contact drum 39^a to its normal extreme position. If, however, the points are so badly damaged that the downward movement of the point detector rod is insufficient to permit the roller 93^a to fully enter the recess 95, or to enter it at all, the spring 69 will act to return the rockshaft and contact drum 39^a to such a position as the position in which the roller 93^a engages the point detector rod will permit.

I will next assume that the slide bar 11 has been moved to its extreme reverse position so that the switch points are in their full reverse positions, and that a train trails the switch. Under these conditions while the train is trailing the switch, the point detector rod D will be moved downwardly as viewed in Figs. 1 and 4, and this downward movement will cause the upper bevel face of the recess 95 to cooperate with the roller 93^b in such manner that the rockshaft 63^b will be rotated in a counter-clockwise direction, thereby moving roller 65^b out of engagement with recess b¹ in motion plate 68, causing spring 69 to be extended, and causing contact drum 39^b to be rotated from its reverse extreme position to its intermediate position. The rotation of the contact drum 39^b under these conditions will first cause contact 47^b—42^b—50^b to become closed, then contacts 45^b—40^b—48^b and 46^b—41^b—49^b to become simultaneously opened, and if the amount of the displacement is sufficiently great, contact 48^b—43^b—49^b, to become closed. After the train has completely trailed the switch, if the switch points then spring back toward their full normal positions far enough to permit the roller 93^b to completely reenter recess 95, spring 69 will act to restore the contact drum 39^b to its full reverse position, but if the points do not spring back toward their full reverse positions far enough to permit the roller 93^b to fully enter the recess 95, or to enter it at all, the contact drum will be returned by the spring to such position as the position in which the roller 93^b engages the detector rod permits.

In actual practice, the contacts 45^a—40^a—48^a and 46^a—41^a—49^a are usually referred to as the normal indication contacts, the contacts 45^b—40^b—48^b and 46^b—41^b—49^b as the reverse indication contacts, the contact 48^a—43^a—49^a as the normal shunting contact, the contact 48^b—43^b—49^b as the reverse shunting contact, the contact 47^a—42^a—50^a as the normal restoring contact, and the contact 47^b—42^b—50^b as the reverse restoring contact. Furthermore, the contacts 48^a—44^a—49^a and 48^b—44^b—49^b are also referred to as shunting contacts, these latter contacts only being provided where the switch operating mechanism is to be used for controlling a switch at a crossover. The function of the various contacts will immediately be recognized from their names by those skilled in the art, and inasmuch as these contacts may be utilized in a variety of well-known circuits none of which form any part of my present invention, it is deemed unnecessary to illustrate any of these circuits here.

Under some conditions, it is desirable to insure that when a train has trailed the switch, an indication of this fact will be given regardless of whether the switch points have been damaged by the trailing train or not. For this purpose, I provide a latching device E comprising a tubular member 96 (see Fig. 5) which is closed at its

lower end by a cap 97, and which is screwed at its upper end into the lower end of a vertical hole 98 provided in the arm 64^a. A latching plunger 99 is mounted to slide within the hole 98 and tubular member 96, and is biased to an upper position by means of a compressed coil spring 100 which surrounds a portion 99^a of reduced diameter formed on the lower end of the latching plunger. The upper end of the latching plunger is also formed with a portion 99^b of reduced diameter which extends upwardly with some clearance through a hole 101 in a lug 102 formed on the crank arm 64^a. The upper portion of the lug 102 is spaced some distance from the arm, and serves both as a guide for the latching plunger and as a means for preventing vertical displacement of a latch head 103 which cooperates with the latching plunger. The latch head 103 is adjustably secured to one end of a latch rod 104, and is formed with an axially extending open end slot 105 which receives the upper end 99^b of the latching plunger with some clearance. The free end of the latch rod 104 is pivotally attached to the arm 64^b by means of a bolt 106. The parts are so proportioned that when the upper end 99^b of the latching plunger engages the latch head 103 at the inner end of the slot 105, as will normally be the case, the crank arms 64^a and 64^b will be held in the relative position in which there is a slight amount of clearance between the rollers 65^a and 65^b and the adjacent sides of the motion plate 68. One advantage of proportioning the parts in this manner is that wear caused by vibration of the motion plate resulting from high speed trains moving over the switch is prevented. The latch head 103 is provided, in addition to the slot 105, with a concave surface 107 (see Figs. 13 and 14) which surface slopes downwardly and rearwardly from the slot 105 at the inner end of this slot, and which has a radius of curvature just a little larger than the radius of curvature of the outer surface of the body of the latching plunger 99. The slope of this concave surface is such that when the upper end portion 99^a of the latching plunger 99 is engaging the slot 105 at the inner end of the slot, the under surface of the latch head adjacent the lower end of the concave surface 107 will overlie the upper surface of the main portion of the latching plunger a predetermined amount, and will thus hold the latching plunger in its lowermost position in which the upper surface of the main portion of the plunger is substantially flush with the top of the hole 98, but that, if the crank arms 64^a and 64^b are moved away from their normal relative positions to which they are biased by the spring 69, due for example, to a roller 93 on one of the crank arms 92 being forced at least partway out of the recess 95 in the point detector rod as a result of movement of the point detector rod caused by a train trailing the switch, the plunger will be permitted to rise to its upper position in which the body of the plunger will engage the latch head 103 adjacent the upper end of the concave surface 107.

With the latching device E constructed in the manner just described, it will be apparent that during reversal of the switch points due to operation of the slide bar 11, the latching device E will have no effect whatever on the circuit controller, and the circuit controller will function in the manner previously pointed out. When, however, a train trails the switch, if the resultant displacement of the switch points is sufficient to cause one or the other of the rollers 93^a and 93^b

to be forced partway out of the recess 95 in the point detector rod due to engagement of such roller with one of the bevel faces of the recess 95, the consequent rotation of the crank 63^a or the 5 crank 63^b, as the case may be, will move the latching plunger and latch head to such relative positions that the under surface of the latch head will no longer overlie the upper surface of the main portion of the latching plunger 99, and 10 when this happens, the spring 100 will then force the latching plunger upwardly, thereby causing further relative rotation of the rockshafts. After the latching plunger has once been moved to its 15 upper position, it will subsequently remain in this position until it is manually restored to its lowermost position by pushing down on the top of the upper portion 99^b of the latching plunger. The parts are so proportioned that when the plunger is in its upper position, if the slide bar 20 then occupies its extreme normal position, the contact drum 39^a will be held in the position in which the normal indication contacts are open even though the switch points substantially 25 spring back to their full normal positions, and that if the slide bar is then in its reverse position, the contact drum 39^b will be held in the position in which the reverse indication contacts are open even though the switch points subsequently spring back to their full reverse position. 30 From the foregoing, it will be seen that a latching device embodying my invention has two essential characteristics. First, it causes the indication contacts of the circuit controller to function in accordance with the position of 35 the point detector rod during the time the switch is actually being trialed, rather than after the train has completely trialed through the switch, and, second, it makes it necessary for a maintainer to go to a switch which has 40 been trialed and manually release the latching device before either set of indication contacts can again become closed. It is assumed that when a maintainer goes to the switch to release the latching device, he will inspect the 45 switch points, and if damaged, repair them, thus guarding against a dangerous condition due to damaged switch points.

The purpose of the slope on concave surface 107 of latch head 103 is to rotate the contact 50 drum which is operating while the switch is being trialed a sufficient additional amount, after the latching device has tripped, so as to insure that the indication contacts controlled by such drum will be opened a sufficient amount 55 to take care of any normal variations which are liable to occur due to slight variations in the dimensions of the parts during manufacture, or to any slight misadjustments of the parts which may occur in service.

60 It should be noted that if spring 69 should break or be of insufficient strength to overcome any binding or friction which might occur between the parts, a dangerous condition will not result because this spring only acts to rotate 65 the contact drums to the positions in which the indication contacts are closed, the rotation of the contact drums in the opposite direction being caused by engagement of the rollers 65^a and 65^b with the motion plate 68, or by engagement 70 of the rollers 93^a and 93^b with the beveled ends of the recess 95 in the point detector rod D.

75 For obvious reasons, it is desirable to be able to check the relation between the locking dogs 19 and 20 and the notches 19^a and 20^a in the lock rod L with which these dogs cooperate,

while the dogs are within the associated notches. In order to permit the relation between the dog 19 and the notch 19^a to be checked when the dog 19 is in the notch 19^a, I provide two windows 108 and 109 (see Figs. 4 and 5) in the bottom wall 35 of the compartment 33 directly above the point where the lock rod L intersects the slide bar 11. These windows are normally closed to prevent dirt from entering the compartment 33 by means of a shutter 110 which is pivoted on a screw 111 secured to the bottom wall 35 of the compartment 33. The shutter 110 may, however, when desired, be rotated to a position in which the windows 108 and 109 coincide with openings 108^a and 109^a formed 15 in the shutter, by means of an upstanding lug 110^a formed on the shutter, which lug is disposed within an opening 112 provided in the insulating member 51.

The relation between the notch 20^a and the 20 dog 20 when the dog 20 is within the notch 20^a may be observed directly by looking under the casing 29 from the left-hand end of the casing, as viewed in Fig. 1.

The proper relation between the locking dog 25 19 and the associated notch 19^a in the lock rod L may be checked indirectly by noting the position of the end surface 113 of the long notch 20^a in the lock rod (see Fig. 6) with respect to the outer end surface 114^a of a lug 114 on the casing 30 29. That is to say, when the outer end surface 114^a on the lug 114 is in vertical alignment with the surface 113, the lock rod is in proper adjustment for locking the switch in its normal extreme position. 35

Similarly, the proper relation between the notch 20^a in the lock rod L and the dog 20 may be indirectly checked by noting that the end surface 115 of the long notch 19^a in lock rod L aligns vertically with the outer end surface 117^a of a lug 117 provided on the casing 29. 40

It should be pointed out that in order to remove the lock rod L from the switch operating mechanism for any reason, it is only necessary to remove two lock rod guides 118 and 119 (see Figs. 2, 3 and 5), which can be done merely by 45 removing a bolt 120 which clamps these guides within suitable recesses formed in the base plate 10 and in the top plate 18.

An important feature of a switch operating 50 mechanism embodying my invention is that by properly assembling the parts, the same parts may be used for either a left-hand or a right-hand switch layout regardless of whether the point adjacent the mechanism is normally closed or normally open; and in addition, the same 55 circuits and circuit connections may be used under all conditions of layout. For example, the layout shown in Fig. 1 is a left-hand layout with the switch point adjacent the switch operating mechanism normally closed. If, now, with 60 this layout, it is desired to have the point adjacent the movement normally open instead of normally closed, and at the same time retain the same circuit connections to the circuit controller as would be used when the point adjacent the switch operating mechanism is normally closed, all that needs to be done is to disconnect the crank arms 62^a and 62^b from the rockshafts 63^a and 63^b, respectively, and connect 65 them with the rockshafts 63^b and 63^a, respectively, as shown in Fig. 15. When this has been done, the operation of the apparatus will be similar to that previously described with the exception that any movement of the rockshaft 70 75

63^a due either to coöperation of the roller 65^a with the recesses a¹ and a² in the motion plate 68, or to cooperation of roller 93^a with the recess 95 in the point detector rod D will operate the contact drum 39^b instead of the contact drum 39^a, and that any movement of the rock-shaft 63^b due either to cooperation of the roller 65^b with the notches b¹ and b² in the motion plate 68, or to cooperation of the roller 93^b with the recess 95 in the point detector rod will now operate the contact drum 39^a instead of drum 39^b.

For a right-hand layout, with the point adjacent the movement normally closed, the parts 15 of the mechanism proper are assembled as shown in Fig. 16, and the parts of the circuit controller are assembled as shown in Fig. 15. From an inspection of Fig. 16, it will be apparent that as here shown, the slide bar 11 has been turned 20 over so that the side which is the upper side in Figs. 1, 2 and 3, is now the lower side, the friction lock and alligator jaw 16 have been disposed in positions reverse to those in which they are shown in Fig. 2, and the lock rod L extends 25 from the side of the switch movement opposite to that in which it extends in Fig. 1. The assembly of the circuit controller as shown in Fig. 15, in so far as the relation of the arms 62^a and 62^b with respect to the rockshafts 63^a and 63^b 30 is concerned, has been described hereinbefore, and need not therefore be repeated here. It will be noted, however, that in addition to the arms 62^a and 62^b being reversed from the positions in which they are shown in Fig. 4, the motion plate 68 has been turned upside down. The 35 operation of the apparatus, as a whole, when assembled as shown in Figs. 15 and 16 is similar to that previously described, and will be readily understood from the foregoing without further 40 detailed description.

If, with the layout shown in Fig. 16, it is desired to have the switch points adjacent the switch operating mechanism normally open instead of normally closed, the arms 62^a and 62^b 45 of the circuit controller will then be secured to the rockshafts 63^a and 63^b, respectively, as shown in Fig. 4, and the motion plate 68 will be secured to the slide bar 11 in the manner shown in Fig. 15. The operation of the apparatus under these 50 conditions is believed to be sufficiently obvious from the foregoing so as not to require any further description.

Referring now to Fig. 17, I have here shown a movable point frog A¹ arranged to be operated 55 by a switch operating mechanism B¹, which latter mechanism also embodies my invention. The frog layout A¹ is of standard construction and comprises the usual stock rails between which are mounted two pairs of switch points, 60 such pairs of switch points being disposed in opposite relation in accordance with the usual practice. The one pair of points is operated between its normal and reverse positions by an operating rod L¹ and has attached thereto a lock rod L¹ and a point detector rod D¹, and the other pair of points is operated between its normal and reverse positions by an operating rod L² and has attached thereto a lock rod L² and a point detector rod D².

The switch operating mechanism B¹ comprises 70 two alligator jaws 125¹ and 125², the one jaw of which 125¹ is operatively connected with the operating rod L¹ in the same manner that the alligator jaw 16 shown in Figs. 1, 2 and 3, is op-

eratively connected with the operating rod 7¹, and the other jaw of which 125² is similarly operatively connected with the operating rod 7². The alligator jaws 125¹ and 125² cooperate with rollers 121 and 122, respectively, carried by the slide bar 126 of the mechanism in such manner that when either jaw is rotated in response to longitudinal movement of the slide bar, the other jaw will be simultaneously rotated in the same direction. It will be apparent, therefore, from an inspection of the drawings that the switch points will simultaneously move in opposite directions when the switch operating mechanism is actuated to reverse the points. The rollers which actuate the two alligator jaws are not shown clearly in the drawings because they are hidden by other parts of the mechanism, but these rollers are each similar to the roller 15 shown in Fig. 2, and are each attached to the slide bar 126 in the same manner that the roller 15 is attached to the slide bar 11. The slide bar 126 in addition to being provided with rollers which actuate the alligator jaws 125¹ and 125² is provided with suitable locking dogs which cooperate with the lock rods L¹ and L² to lock both pairs of points in both extreme positions of the points in a well-known manner. The lock rods are held in the proper positions relative to the slide bar by means of lock rod guides similar to the lock rod guides 118 and 119 previously described. The point detector rods D¹ and D² are slidably mounted in suitable guideways provided in the base plate of the operating mechanism B¹, and these point detector rods cooperate with the circuit controller of the mechanism in a manner which I will describe presently. The remaining parts of the switch operating mechanism B¹ not specifically mentioned are similar in all respects to those shown in Figs. 1, 2 and 3, and it is believed that the operation of this portion of the mechanism will be readily understood from the foregoing and from an inspection of the drawings without further description.

The circuit controller for the mechanism B¹ is designated C¹, and is similar to the previously described circuit controller C in so far as the means for detecting the positions of the points to which the point detector rod D¹ is attached and the means for checking the position of the slide bar are concerned. However, in order to detect the position of the points to which the point detector rod D² is attached additional means are necessary as shown in Figs. 19 and 20. Referring to Figs. 19 and 20, these additional means comprise two rockshafts 130^a and 130^b 55 which are journaled on opposite sides of the slide bar 126 within suitable bearings formed in lugs 131 attached to one side wall of the compartment 34. The rockshaft 130^a is provided at its lower end with a crank arm 132^a and at its upper end, with a crank arm 133^a, while the rockshaft 130^b is provided at its lower end with a crank arm 132^b, and at its upper end with a crank arm 133^b. The crank arm 132^a carries a roller 134^a which is adapted to enter the recess 95 in the point detector rod D² when and only when the pair of points to which the rod D² is attached occupy the positions in which they are shown in the drawings, and the crank arm 132^b similarly carries a roller 134^b which is adapted to enter the recess 95 in the point detector rod D² when and only when the switch points occupy the positions opposite to those in which they are shown in the drawings. The crank 60 65 70 75

arm 133^a is pivotally connected at its free end to one end of an adjustable link 135^a the other end of which is pivotally connected with the crank arm 62^a by means of the eccentric stud 81^a. Crank arm 133^b is likewise pivotally connected at its free end to one end of an adjustable link 135^b, the other end of which is pivotally connected with the crank arm 62^b by means of the eccentric stud 81^b. The parts are so proportioned that when the switch points are in their normal positions, the roller 134^a will be prevented from entering the recess 95 in the point detector rod D² unless the recess 95 in the point detector rod D¹ is then in such a position that the roller 93^a can simultaneously enter this latter recess, and vice versa, and that when the switch points are in their reverse positions, the roller 134^b will be prevented from entering the recess 95 in the point detector rod D² unless the point detector rod D¹ then occupies the position in which the recess 95 in this detector rod aligns with the roller 93^b, and vice versa. The parts are further so proportioned that movement of the rockshaft 130^a caused by a given displacement of the switch points with which the point detector rod D² is connected, from their normal extreme positions, will rotate the rockshaft 63^a in the same direction and the same amount as this latter rockshaft would be rotated by a corresponding displacement from their normal positions of the switch points with which the point detector rod D¹ is connected, and that when the switch points are in their reverse positions, any rotation of the rockshaft 130^b caused by displacement of the switch points with which the point detector rod D² is connected will cause the rockshaft 63^b to be rotated in the same direction and the same amount as this latter rockshaft would be rotated due to a corresponding displacement of the switch points with which the point detector rod D¹ is connected. It will be apparent, therefore, that with the circuit controller constructed in the manner just described corresponding displacements of either pair of switch points from their normal positions when they are locked in these positions will operate the contact drum 39^a to give an indication of such displacement and that displacement of either pair of points from their reverse positions when the points are locked in these positions will operate the contact drum 39^b to give an indication of this displacement.

One advantage of switch operating apparatus embodying my invention is that a minimum number of parts are required, all of which can be easily and cheaply manufactured.

Another advantage of switch operating apparatus embodying my invention is that the same parts may be used for all conditions of layout by properly rearranging the parts.

Still another advantage of switch operating apparatus embodying my invention is that all parts are readily accessible, thus greatly facilitating inspection and maintenance of the mechanism.

Although I have herein shown and described only a few forms of railway switch operating apparatus embodying my invention, it is understood that various changes and modifications may be made therein within the scope of the appended claims without departing from the spirit and scope of my invention.

Having thus described my invention, what I claim is:

75 1. In combination, a railway switch, a slide

bar movable longitudinally between two extreme positions and operatively connected with the switch in such manner that movement of said slide bar between its two extreme positions will move the switch between its two extreme positions, a rockshaft, an arm secured to said rockshaft and provided with a roller, a motion plate secured to said slide bar and provided with a first recess which is adapted to receive said roller and which aligns with said roller when and only when said slide bar occupies one extreme position and with a second recess which is also adapted to receive said roller and which aligns with said roller when said slide bar occupies any position intermediate its two extreme positions, the parts being so proportioned that said rockshaft will be rotated to one extreme position when said roller enters said first recess, to an intermediate position when said roller enters said second recess, and to another extreme position when said roller is forced out of both recesses, a spring operatively connected with said rockshaft for biasing said rockshaft in the direction to cause said roller to enter said recesses, and a circuit controlling element controlled in accordance with the position of said rockshaft.

2. In combination, a railway switch, a slide bar movable longitudinally between two extreme positions and operatively connected with the switch in such manner that movement of said slide bar between its two extreme positions will move the switch between its two extreme positions, a rockshaft, an arm secured to said rockshaft and provided with a roller, a motion plate secured to said slide bar and provided with a first recess which is adapted to receive said roller and which aligns with said roller when and only when said slide bar occupies one extreme position and with a second recess which is also adapted to receive said roller and which aligns with said roller when said slide bar occupies any position intermediate its two extreme positions, the parts being so proportioned that said rockshaft will be rotated to one extreme position when said roller enters said first recess, to an intermediate position when said roller enters said second recess, and to another extreme position when said roller is forced out of both recesses, a spring operatively connected with said rockshaft for biasing said rockshaft in the direction to cause said roller to enter said recesses, and a plurality of contacts selectively operated in accordance with the position of said rockshaft.

3. In railway switch operating apparatus, in combination, a slide bar movable between two extreme positions and operatively connected with the switch in such manner that movement of said slide bar between its two extreme positions will move the switch between its two extreme positions, a rockshaft, an arm secured to said rockshaft and provided with a roller, a motion plate operatively connected with said slide bar and provided with two recesses one of which aligns with said roller when and only when said slide bar occupies one extreme position and the other of which aligns with said roller at all times except when said slide bar occupies either of its two extreme positions, means for biasing said rockshaft in the direction to cause said roller to enter said recesses, and a circuit controlling member operatively connected with said rockshaft, the parts being so proportioned that said circuit controlling member will be rotated to one extreme position, to an intermediate position, or to another

extreme position according as said roller enters said one recess, said other recess, or is forced out of both recesses.

4. In railway switch operating apparatus, in combination, a slide bar movable longitudinally between two extreme positions and operatively connected with the switch in such manner that movement of said slide bar from either extreme position to the other extreme position first unlocks the switch points, then reverses them, and finally relocks the switch points in their reverse positions, a rockshaft, an arm secured to said rockshaft and provided with a roller, a motion plate operatively connected with said slide bar and provided with two recesses one of which aligns with said roller when and only when said slide bar occupies one extreme position and the other of which aligns with said roller at all times except when said slide bar occupies either of its extreme positions, means for biasing said rockshaft to a position in which said roller will enter said recesses when said recesses are in alignment with said roller, and a circuit controlling member operatively connected with said rockshaft, the parts being so proportioned that said circuit controlling member will be rotated to one extreme position, to an intermediate position, or to another extreme position according as said roller enters said one recess, said other recess, or is forced out of both recesses.

5. In combination, a railway switch, a slide bar movable longitudinally between two extreme positions and operatively connected with the switch in such manner that movement of said slide bar between its two extreme positions will move the switch between its two extreme positions, a rockshaft, a first arm secured to said rockshaft and provided with a first roller, a motion plate secured to said slide bar and provided with a first recess which aligns with said first roller when and only when said slide bar occupies one extreme position and with a second recess which aligns with said first roller at all times except when said slide bar occupies either of its two extreme positions, a spring operatively connected with said rockshaft for biasing said rockshaft to a position in which said first roller will enter said recesses when said recesses are in alignment with said first roller, the parts being so proportioned that said rockshaft will be rotated to one extreme position when said first roller enters said first recess, to an intermediate position when said roller enters said second recess, and to another extreme position when said roller is forced out of both recesses, a second arm secured to said rockshaft and provided with a second roller, a point detector rod secured to the switch points and provided with a third recess which aligns with said second roller only when the switch is in the extreme position corresponding to the extreme position of the slide bar in which said first recess aligns with said first roller, the parts being further so proportioned that said second roller will enter said third recess when and only when said first roller enters said first recess, and a circuit controlling element controlled in accordance with the position of said rockshaft.

6. In combination, a railway switch, a slide bar movable longitudinally between two extreme positions and operatively connected with the switch in such manner that movement of said slide bar between its two extreme positions will move the switch between its two extreme positions, a rockshaft, a first arm secured to said rockshaft and

provided with a first roller, a motion plate secured to said slide bar and provided with a first recess which aligns with said first roller when and only when said slide bar occupies one extreme position and with a second recess which aligns with said first roller at all times except when said slide bar occupies either of its two extreme positions, a spring operatively connected with said rockshaft for biasing said rockshaft in the direction to cause said first roller to enter said recesses, the parts being so proportioned that said rockshaft will be rotated to one extreme position when said first roller enters said first recess, to an intermediate position when said roller enters said second recess, and to another extreme position when said roller is forced out of both recesses, a second arm secured to said rockshaft and provided with a second roller, a point detector rod secured to the switch points and provided with a third recess which aligns with said second roller only when the switch is in the extreme position corresponding to the extreme position of the slide bar in which said first recess aligns with said first roller, the parts being further so proportioned that said second roller will enter said third recess when and only when said first roller enters said first recess, and a plurality of contacts selectively controlled in accordance with the position of said rockshaft.

7. In combination, a railway switch, a slide bar movable longitudinally between two extreme positions and operatively connected with the switch in such manner that movement of said slide bar between its two extreme positions will move the switch between its two extreme positions, a rockshaft, a first arm secured to said rockshaft and provided with a first roller, a motion plate secured to said slide bar and provided with a first recess which aligns with said first roller when and only when said slide bar occupies one extreme position and with a second recess which aligns with said first roller at all times except when said slide bar occupies either of its two extreme positions, a spring operatively connected with said rockshaft for biasing said rockshaft in the direction to cause said roller to enter said recesses, the parts being so proportioned that said rockshaft will be rotated to one extreme position when said first roller enters said first recess, to an intermediate position when said roller enters said second recess, and to another extreme position when said roller is forced out of both recesses, a second arm secured to said rockshaft and provided with a second roller, a point detector rod secured to the switch points and provided with a third recess which aligns with said second roller only when the switch is in the extreme position corresponding to the extreme position of the slide bar in which said first recess aligns with said first roller, the parts being further so proportioned that said second roller will enter said third recess when and only when said first roller enters said first recess, a third arm secured to said rockshaft, a rack bar operatively connected with said third arm in such manner that rotation of said rockshaft between its two extreme positions will cause reciprocation of said rack bar between two extreme positions, said rack bar being provided with rack teeth, a rotatable contact drum provided with a gear wheel meshing with said rack teeth, and a plurality of contacts selectively controlled by said contact drum in accordance with the position of the contact drum.

8. In combination, a railway switch, a slide bar movable longitudinally between two extreme po-

sitions and operatively connected with the switch in such manner that movement of said slide bar between its two extreme positions will move the switch between its two extreme positions, a rock- 5 shaft, a first crank arm secured to said rockshaft and provided with a first roller, a motion plate secured to said slide bar and provided with a first recess which aligns with said first roller when and only when said slide bar occupies one ex- 10 treme position and with a second recess which aligns with said first roller at all times except when said slide bar occupies either of its two ex- 15 treme positions, a spring operatively connected with said rockshaft for biasing said rockshaft in the direction to cause said first roller to enter said recesses, the parts being so proportioned that said rockshaft will be rotated to one extreme position when said first roller enters said first recess, to an intermediate position when said roller enters 20 said second recess, and to another extreme position when said roller is forced out of both recesses, a second arm secured to said rockshaft and provided with a second roller, a point detector rod secured to the switch points and provided 25 with a third recess which aligns with said second roller only when the switch is in the extreme position corresponding to the extreme position of the slide bar in which said first recess aligns with said first roller, the parts being further so proportioned that said second roller will enter said third recess when and only when said first roller enters said first recess, a third arm secured to said rock- 30 shaft, a rack bar operatively connected with said third arm in such manner that rotation of said rockshaft between its two extreme positions will cause reciprocation of said rack bar between two extreme positions, said rack bar being provided with rack teeth, a rotatable contact drum provided with a gear wheel meshing with said rack teeth, a 35 plurality of contacts selectively controlled by said contact drum in accordance with the position of the contact drum, means for adjusting the position of said first roller relative to said first arm, and other means for adjusting the position of said third arm relative to said rockshaft.

9. In combination, a railway switch, a slide bar movable longitudinally between two extreme positions and operatively connected with the switch in such manner that movement of said slide bar between its two extreme positions will move the switch between its two extreme positions, a rockshaft, a first arm secured to said rockshaft and provided with a first roller, a motion plate secured to said slide bar and provided 50 with a first recess which aligns with said first roller when and only when said slide bar occupies one extreme position and with a second recess which aligns with said first roller at all times except when said slide bar occupies either of its two extreme positions, a spring operatively connected with said rockshaft for biasing said rockshaft in the direction to cause said first roller to enter said recesses, the parts being so proportioned that said rockshaft will be rotated to one 55 extreme position when said first roller enters said first recess, to an intermediate position when said roller enters said second recess, and to another extreme position when said roller is forced out of both recesses, a second arm secured to said rock- 60 shaft and provided with a second roller, a point detector rod secured to the switch points and provided with a third recess which aligns with said second roller only when the switch is in the extreme position corresponding to the extreme 65 position of the slide bar in which said first recess

aligns with said first roller, the parts being further so proportioned that said second roller will enter said third recess when and only when said first roller enters said first recess, a circuit controlling element controlled in accordance with the position of said rockshaft, and means effective if said second roller is forced out of said third recess due to movement of said point detector rod for latching said rockshaft in its intermediate position until said rockshaft is subsequently manually released. 5

10. The combination with a railway switch and a slide bar movable longitudinally between two extreme positions and operatively connected with the switch for moving the switch between its two extreme positions, of a circuit controller comprising two rockshafts each provided with an arm carrying a roller, a spring connected between said arms for biasing each of said arms to one position, two rotatable contact drums one operatively connected with each rockshaft, and a motion plate secured to said slide bar and cooperating with both said rollers for actuating said rockshafts to actuate said contact drums in accordance with the positions of said slide bar. 20

11. The combination with a railway switch and a slide bar movable longitudinally between two extreme positions and operatively connected with the switch for moving the switch between its two extreme positions, of a circuit controller comprising two rockshafts each provided with an arm carrying a roller, a spring connected between said arms for biasing each of said arms to one position, two rotatable contact drums one operatively connected with each rockshaft, and a motion plate secured to said slide bar and provided in its opposite edges with recesses which cooperate with said rollers. 30

12. The combination with a railway switch and a slide bar movable longitudinally between two extreme positions and operatively connected with the switch for moving the switch between its two extreme positions, of a circuit controller comprising a first and a second rockshaft journaled on opposite sides of said slide bar, a first arm secured to said first rockshaft and provided with a first roller, a second arm secured to said second rockshaft and provided with a second roller, a motion plate secured to said slide bar and disposed between said rollers, said motion plate being provided in its one edge with a first recess which aligns with said first roller when and only when said slide bar occupies one extreme position and with a second recess which aligns with said first roller at all times except when said slide bar occupies either of its two extreme positions and which is approximately one half as deep as said first recess, said motion plate also being provided in its other edge with a third recess which aligns with said second roller when and only when said slide bar occupies the other extreme position and with a fourth recess which aligns with said second roller at all times except when said slide bar occupies either of its two extreme positions and which is approximately half as deep as said third recess, the parts being so proportioned that movement of said rockshafts due to cooperation of said rollers with said recesses will always be equal and opposite, and two circuit controlling elements one controlled by each rockshaft. 55

13. In railway switch operating apparatus of the type in which a railway switch is moved between normal and reverse positions in response to longitudinal movements of a slide bar between corresponding extreme positions, the combination 70

with a motion plate which is intended to be attached to said slide bar to be actuated thereby and which actuates circuit controlling means through the medium of a specially shaped edge 5 producing a lateral thrust on a spring biased member in response to longitudinal movements of the motion plate, of means for securing said motion plate to said slide bar in such manner that said motion plate is constrained to move longitudinally in response to longitudinal movements 10 of said slide bar but is permitted to move laterally a limited amount relative to said slide bar, and fixed means cooperating with said motion plate for preventing lateral movement of said motion plate due to lateral movements of said slide 15 bar.

14. In railway switch operating apparatus of the type in which a railway switch is moved between normal and reverse positions in response 20 to longitudinal movements of a slide bar between two extreme positions, the combination with a motion plate which is adapted to be carried on top of, and driven by, said slide bar, and which is arranged to actuate circuit controlling means 25 through the medium of recesses formed in at least one edge of said motion plate, of means for securing said motion plate to said slide bar in such manner that said motion plate is constrained to move longitudinally in response to longitudinal 30 movements of said slide bar but is permitted to move laterally a limited amount relative to said slide bar, and fixed means cooperating with said motion plate for preventing lateral movement of said motion plate.

15. In combination, a slide bar movable longitudinally between two extreme positions and adapted to be operatively connected with a railway switch for moving the switch between its two extreme positions, a motion plate secured to said 40 slide bar in such manner that said motion plate is constrained to move longitudinally in response to longitudinal movements of said slide bar but that said motion plate is free to move laterally with respect to said slide bar a limited amount, 45 said motion plate being provided with a longitudinally extending groove in its upper face and with a recess in one side edge, circuit controlling means biased into engagement with said one side edge of said motion plate and arranged to co- 50 operate with said recess, and a fixed tongue extending into said groove and cooperating therewith to hold said motion plate in a fixed lateral position, whereby lateral movements of said slide bar will not be transmitted to said circuit con- 55 trolling means.

16. In combination, a slide bar movable longitudinally between two extreme positions and operatively connected with a railway switch for moving the switch between its two extreme positions, a motion plate secured to said slide bar in such manner that said motion plate is constrained to move longitudinally in response to longitudinal movements of said slide bar but that a limited amount of lateral motion between said 60 motion plate and said slide bar is permitted, said slide bar being provided in one of its edges with a recess, a roller biased into engagement with said one edge of said motion plate and cooperating with said recess, circuit controlling means controlled by said roller, and means for holding said motion plate in a fixed lateral position while permitting longitudinal movements of the motion plate, whereby thrusts transmitted to said slide bar due to trains moving over said switch will 65

not be transmitted to said circuit controlling means.

17. In combination, a slide bar movable longitudinally between two extreme positions and operatively connected with a railway switch for 5 moving the switch between its two extreme positions, a motion plate mounted on top of said slide bar and provided adjacent one end with a rectangular slot extending transversely of said motion plate, a bolt secured to said slide bar and 10 provided with a head which is wider than said slot and with a rectangular portion adjacent said head which extends through said slot and cooperates with said slot in such manner that said motion plate is constrained to move longitudinally in response to longitudinal movements 15 of said slide bar but that said motion plate is permitted to move laterally a limited amount relative to said slide bar, fixed means cooperating with said motion plate for preventing lateral 20 movement of said motion plate while permitting free longitudinal movement of said motion plate, and circuit controlling means cooperating with said motion plate at its edges and arranged to be moved toward and away from said motion plate 25 in response to longitudinal movement of said motion plate.

18. In railway switch operating apparatus of the type in which a railway switch is moved between normal and reverse positions in response to 30 longitudinal movements of a slide bar between two extreme positions, the combination with a motion plate which is intended to be attached to said slide bar with one face up for one condition of operation of the apparatus and with the 35 opposite face up for another condition of operation of the apparatus and which is provided with an axially extending longitudinal groove in each face and with a transversely disposed rectangular slot adjacent one end and with similar oppositely 40 disposed recesses in its opposite side edges for cooperation with spring biased circuit controller actuating members, of means for securing said motion plate to said slide bar with either face up comprising a bolt fastened to said slide bar and 45 provided with a head which is wider than said slot and with a rectangular portion adjacent said head which extends through said slot and which cooperates with said slot in such manner that said motion plate is constrained to move longitudinally in response to longitudinal movements 50 of said slide bar but is permitted to move laterally relative to said slide bar a limited amount, and a fixed tongue extending into and cooperating with the groove in which ever face of the 55 motion plate is up to prevent said motion plate from moving laterally in response to lateral movement of said slide bar.

19. In railway switch operating apparatus of the type in which a railway switch is moved between normal and reverse positions in response to 60 longitudinal movements of a slide bar between corresponding extreme positions, in combination, a first and a second rockshaft journaled on opposite sides of said slide bar, a first crank arm 65 secured to said first rockshaft and extending substantially parallel to said slide bar and provided with a first roller, a second crank arm secured to said second rockshaft and extending substantially parallel to said slide bar opposite 70 said first crank arm and provided with a second roller, a spring connected between said first and second crank arms and acting to bias said arms toward each other, a motion plate secured to said slide bar and disposed between said first and 75

second rollers and provided in one edge with a first and second recess and in the other edge with a third and fourth recess, said first and second recess being so disposed that said first recess will align with said first roller when and only when said slide bar occupies the extreme position corresponding to the normal extreme position of the switch and that said second recess will align with said first roller at all times except when said slide bar occupies one or the other of its two extreme positions, and said third and fourth recesses being so disposed that said third recess will align with said second roller when and only when said slide bar occupies the extreme position corresponding to the reverse extreme position of the switch and that said fourth recess will align with said second roller at all times except when said slide bar occupies one or the other of its two extreme positions, the parts being so proportioned that said first rockshaft will be rotated to one extreme position when said first roller enters said first recess, to an intermediate position when said first roller enters said second recess, and to another extreme position when said first roller is forced out of both said first and second recesses, and that said second rockshaft will be rotated to one extreme position when said first roller enters said third recess, to an intermediate position when said second roller enters said fourth recess, and to another extreme position when said second roller occupies one or the other of its two extreme positions, the parts being so proportioned that said first rockshaft will be rotated to one extreme position when said first roller enters said first recess, to an intermediate position when said first roller enters said second recess, and to another extreme position when said first roller is forced out of both said first and second recesses, and that said second rockshaft will be rotated to one extreme position when said first roller enters said third recess, to an intermediate position when said second roller enters said fourth recess, and to another extreme position when said second roller occupies one or the other of its two extreme positions, the parts being so proportioned that said first and second rockshafts respectively or with said second and first rockshafts respectively.

20. In railway switch operating apparatus of the type in which a railway switch is moved between normal and reverse positions in response to longitudinal movements of a slide bar between corresponding extreme positions, in combination, a first and a second rockshaft journaled on opposite sides of said slide bar, a first crank arm secured to said first rockshaft and extending substantially parallel to said slide bar and provided with a first roller, a second crank arm secured to said second rockshaft and extending substantially parallel to said slide bar opposite said first crank arm and provided with a second roller, a spring connected between said first and second crank arms and acting to bias said arms toward each other, a motion plate secured to said slide bar and disposed between said first and second rollers and provided in one edge with a first and second recess and in the other edge with a third and fourth recess, said first and second recess being so disposed that said first recess will align with said first roller when and only when said slide bar occupies the extreme position corresponding to the normal extreme position of the switch and that said second recess will align with said first roller at all times except when said slide bar occupies one or the other of its two extreme positions, and said third and fourth recesses being so disposed that said third recess will align with said second roller when and only when said slide bar occupies the extreme position corresponding to the reverse extreme position of the switch and that said fourth recess will align with said second roller at all times except when said slide bar occupies one or the other of its two extreme positions, the parts being so proportioned that said first rockshaft will be rotated to one extreme

position when said first roller enters said first recess, to an intermediate position when said first roller enters said second recess, and to another extreme position when said first roller is forced out of both said first and second recesses, and that said second rockshaft will be rotated to one extreme position when said first roller enters said third recess, to an intermediate position when said second roller enters said fourth recess, and to another extreme position when said second roller is forced out of both said third and fourth recesses, a third crank arm secured to said first rockshaft and provided with a third roller, a fourth crank arm secured to said second rockshaft and provided with a fourth roller, a point detector rod secured to the switch points and provided with a fifth recess which aligns with said third roller when and only when the switch points occupy their extreme normal positions and which aligns with said fourth roller when and only when the switch points occupy their extreme reverse positions, said third and fourth arms and said fifth recess being so designed that movement of said third roller into and out of said fifth recess will rotate said first rockshaft between its one extreme position and its intermediate position, and circuit controlling means separately controlled by said two rockshafts respectively.

21. In railway switch operating apparatus of the type in which a railway switch is moved between normal and reverse positions in response to longitudinal movements of a slide bar between corresponding extreme positions, in combination, a first and a second rockshaft journaled on opposite sides of said slide bar, a first crank arm secured to said first rockshaft and extending substantially parallel to said slide bar and provided with a first roller, a second crank arm secured to said second rockshaft and extending substantially parallel to said slide bar opposite said first crank arm and provided with a second roller, a spring connected between said first and second crank arms and acting to bias said arms toward each other, a motion plate secured to said slide bar and disposed between said first and second rollers and provided in one edge with a first and second recess and in the other edge with a third and fourth recess, said first and second recess being so disposed that said first recess will align with said first roller when and only when said slide bar occupies the extreme position corresponding to the normal extreme position of the switch and that said second recess will align with said first roller at all times except when said slide bar occupies one or the other of its two extreme positions, and said third and fourth recesses being so disposed that said third recess will align with said second roller when and only when said slide bar occupies the extreme position corresponding to the reverse extreme position of the switch and that said fourth recess will align with said second roller at all times except when said slide bar occupies one or the other of its two extreme positions, the parts being so proportioned that said first rockshaft will be rotated to one extreme position when said first roller enters said first recess, to an intermediate position when said first roller enters said second recess, and to another extreme position when said first roller is forced out of both said first and second recesses, and that said second rockshaft will be rotated to one ex-

trema position when said first roller enters said third recess, to an intermediate position when said second roller enters said fourth recess, and to another extreme position when said second 5 roller is forced out of both said third and fourth recesses, a third crank arm secured to said first rockshaft and provided with a third roller, a fourth crank arm secured to said second rockshaft and provided with a fourth roller, a point 10 detector rod secured to the switch points and provided with a fifth recess which aligns with said third roller when and only when the switch points occupy their extreme normal positions and which aligns with said fourth roller when and 15 only when the switch points occupy their extreme reverse positions, said third and fourth arms and said fifth recess being so designed that movement of said third roller into and out of said fifth recess will rotate said first rockshaft between its 20 one extreme position and its intermediate position and that movement of said fourth roller into and out of said fifth recess will rotate said second rockshaft between its one extreme position and its intermediate position, two rotatable contact 25 drums, and means for operatively connecting said two contact drums with said first and second rockshafts respectively or with said second and first rockshafts respectively.

22. In railway switch operating apparatus of the type in which a railway switch is moved between normal and reverse positions in response to longitudinal movements of a slide bar between corresponding extreme positions, in combination, a first and a second rockshaft journaled on opposite sides of said slide bar, a first crank arm secured to said first rockshaft and extending substantially parallel to said slide bar and provided with a first roller, a second crank arm secured to said second rockshaft and extending substantially parallel to said slide bar opposite said first crank arm and provided with a second roller, a spring connected between said first and second crank arms and acting to bias said arms toward each other, a motion plate secured to said slide 40 bar and disposed between said first and second rollers and provided in one edge with a first and second recess and in the other edge with a third and fourth recess, said first and second recess being so disposed that said first recess will align with said first roller when and only when said slide bar occupies the extreme position corresponding to the normal extreme position of the switch and that said second recess will align with said first roller at all times except when said slide 45 bar occupies one or the other of its two extreme positions, and said third and fourth recesses being so disposed that said third recess will align with said second roller when and only when said slide bar occupies the extreme position corresponding to the reverse extreme position of the switch and that said fourth recess will align with said second roller at all times except when said slide bar occupies one or the other of its two extreme positions, the parts being so proportioned that said 50 first rockshaft will be rotated to one extreme position when said first roller enters said first recess, to an intermediate position when said first roller enters said second recess, and to another extreme position when said first roller is forced out of both said first and second recesses, and that said second rockshaft will be rotated to one extreme position when said first roller enters said third recess, to an intermediate position when said second roller enters said fourth recess, and to another extreme position when said second roller 55

is forced out of both said third and fourth recesses, a third crank arm secured to said first rockshaft and provided with a third roller, a fourth crank arm secured to said second rockshaft and provided with a fourth roller, a point 5 detector rod secured to the switch points and provided with a fifth recess which aligns with said third roller when and only when the switch points occupy their extreme normal positions and which aligns with said fourth roller when and 10 only when the switch points occupy their extreme reverse positions, said third and fourth arms and said fifth recess being so designed that movement of said third roller into and out of said fifth recess will rotate said first rockshaft between its 15 one extreme position and its intermediate position and that movement of said fourth roller into and out of said fifth recess will rotate said second rockshaft between its one extreme position and its intermediate position, a first and a second 20 rotatable contact drum, a first gear wheel secured to one end of said first drum, a second gear wheel secured to one end of said second drum, a first rack bar provided in one end with rack teeth which mesh with said first gear wheel 25 and in the other end with a transverse slot, a second rack bar provided in one end with rack teeth which mesh with said second gear wheel and in the other end with a transverse slot, a fifth crank arm provided in one end with a pin 30 which cooperates with the slot in said first rack bar to operatively connect said fifth crank arm with said first rack bar, a sixth crank arm provided in one end with a pin which cooperates 35 with the slot in said second rack bar to operatively connect said sixth crank arm with said second rack bar, and means for securing the free ends of said crank arms to said first and second rockshafts, respectively, or to said second and first rockshafts, respectively. 40

23. In railway switch operating apparatus of the type in which a slide bar carries locking dogs that cooperate with notches in a lock rod to lock the switch points in their extreme positions and in which a circuit controller casing partly encloses said lock rod and said slide bar at their point of intersection in such a way that a view of at least one of the locking dogs when it is in the cooperating notch is cut off by the bottom and side walls of the casing, the combination of 45 a window provided in the bottom wall of the casing, and a shutter pivotally secured to the upper side of said bottom wall and provided with an opening, said shutter being rotatable between a position in which said opening aligns with said 50 window and a position in which said window is closed by said shutter. 55

24. In railway switch operating apparatus, in combination, a lock rod adjustably connected with the switch points and provided with two 60 spaced notches, a slide bar movable between normal and reverse positions and operatively connected with the switch to move the switch between its normal and reverse positions, said slide bar being provided with two locking dogs one of 65 which enters the one notch in said lock rod when the slide bar is moved to its normal extreme position to lock the switch points in their normal extreme positions and the other of which enters the other notch in said lock rod when the slide 70 bar is moved to its reverse extreme position to lock the switch points in their reverse extreme positions, and a circuit controller housing partly enclosing said lock rod and said slide bar adjacent the point where the locking dogs enter the 75

cooperating notches in the lock rod, the combination with the aforementioned instrumentalities of two lugs on the side of said casing so disposed that when the switch is in its normal extreme position the outer end of the one lug will align with one end of said other notch if the lock rod is then properly adjusted for said one locking dog to properly cooperate with said one notch and that when the switch is in its reverse extreme position the outer end of the one lug will align with one end of said one notch if the lock rod is then properly adjusted for said other locking dog to properly cooperate with said other notch.

25. In combination with a movable point frog, a slide bar reciprocable between a normal and a reverse position and operatively connected with both pairs of points of the frog in such manner that movement of said slide bar between its two extreme positions will simultaneously move both pairs of points in opposite directions between their corresponding extreme positions, a first and a second rockshaft journaled on opposite sides of said slide bar, a first crank arm secured to said first rockshaft and extending substantially parallel to said slide bar and provided with a first roller, a second crank arm secured to said second rockshaft and extending substantially parallel to said slide bar opposite said first crank arm and provided with a second roller, a spring connected between said first and second crank arms and acting to bias said arms toward each other, a motion plate secured to said slide bar and disposed between said first and second rollers and provided in one edge with a first and a second recess and in the other edge with a third and a fourth recess, said first and second recesses being so disposed that said first recess will align with said first roller when and only when said slide bar occupies the extreme position corresponding to the normal extreme position of the frog points and that said second recess will align with said first roller at all times except when said slide bar occupies one or the other of its two extreme positions, and said third and fourth recesses being so disposed that said third recess will align with said second roller when and only when said slide bar occupies the extreme position corresponding to the reverse extreme position of the frog points and that said fourth recess will align with said second roller at all times except when said slide bar occupies one or the other of its two extreme positions; the parts being so proportioned that said first rockshaft will be rotated to one extreme position when said first roller enters said first recess, to an intermediate position when said first roller enters said second recess, and to another extreme position when said first roller is forced out of both said first and second recesses, and that said second rockshaft will be rotated to one extreme position when said first roller enters said third recess, to an intermediate position when said second roller enters said fourth recess, and to another extreme position when said second roller is forced out of both said third and fourth recesses; a third crank arm secured to said first rockshaft and provided with a third roller, a fourth crank arm secured to said second rockshaft and provided with a fourth roller, a first point detector rod secured to the one pair of frog points and provided with a fifth recess which aligns with said third roller when and only when the pair of points to which said first detector rod

is attached is in its extreme normal position and the then closed point of such pair is tight against the associated fixed rail and which fifth recess aligns with said fourth roller when and only when the points of said one pair are in their extreme reverse position and the then closed point is tight against the associated fixed rail, said third and fourth arms being so designed that movement of said third roller into or out of said fifth recess will rotate said first rockshaft between its one extreme position and its intermediate position and that movement of said fourth roller into and out of said fifth recess will rotate said second rockshaft between its one extreme position and its intermediate position, a first and a second rotatable contact drum, a first gear wheel secured to one end of said first drum, a second gear wheel secured to one end of said second drum, a first rack bar provided in one end with rack teeth which mesh with said first gear wheel and in the other end with a transverse slot, a second rack bar provided in one end with rack teeth which mesh with said second gear wheel and in the other end with a transverse slot, a fifth crank arm provided in one end with a pin which cooperates with the slot in said first rack bar to operatively connect said fifth crank arm with said first rack bar, a sixth crank arm provided in one end with a pin which cooperates with the slot in said second rack bar to operatively connect said sixth crank arm with said second rack bar, means for securing the free ends of said fifth and sixth crank arms to said first and second rockshafts respectively, third and fourth rockshafts journaled on opposite sides of said slide bar, said third rockshaft being provided with a seventh crank arm carrying a fifth roller and with an eighth crank arm and said fourth rockshaft being provided with a ninth crank arm carrying a sixth roller and with a tenth crank arm, a second detector rod connected with the other pair of frog points and provided with a sixth recess which aligns with said fifth roller when and only when said other pair of points occupy their extreme normal position and the then closed point is tight against the associated fixed rail and which sixth recess aligns with said sixth roller when and only when said other pair of points occupy their extreme reverse positions and the then closed point is tight against the associated fixed rail, a first link pivotally connected at one end with the free end of said eighth crank arm and at the other end with said fifth crank arm at a point intermediate the ends of this latter crank arm, a second link pivotally connected at one end with the free end of said tenth crank arm and at the other end with said sixth crank arm at a point intermediate the ends of this latter crank arm, said sixth recess and said seventh, eighth, ninth and tenth crank arms being so designed that movement of said fifth roller into and out of said sixth recess will rotate said first rockshaft between its one extreme position and its intermediate position and that movement of said sixth roller into and out of said sixth recess will rotate said second rockshaft between its one extreme position and its intermediate position.

26. In combination with a railway switch and operating mechanism for said switch including a driving member movable between two extreme positions for moving the switch to its extreme positions, a point detector rod positioned in accordance with the position of the switch, a cir-

- cuit controlling element movable to an intermediate and two extreme positions, biasing means effective when and only when said switch occupies one extreme position for moving said circuit controlling element to one extreme position, means controlled by said detector rod and effective upon displacement of the switch points when the switch occupies its one extreme position for moving said circuit controlling element to its intermediate position, means controlled by said driving member and effective upon movement of said driving member from one extreme position to the other extreme position to move the switch from its one extreme position to its other extreme position for moving said circuit controlling element to its intermediate position before the switch points start to move and to its other extreme position after the movement of the points to their other extreme positions has been completed, and latch mechanism effective upon displacement of the switch points away from said one extreme position while said driving member is in the corresponding extreme position to prevent said circuit controlling element from returning to its one extreme position.
27. In combination with a railway switch and operating mechanism for said switch comprising a driving member movable between two extreme positions for actuating said switch to its extreme positions, a detector rod positioned in accordance with the position of said switch, two contact mechanisms each having normal and reverse positions, two actuating members each controlled by said detector rod and by said driving member and normally moving in unison, means controlled by each actuating member for separately driving a different one of said contact mechanisms to its normal or reverse position according as the switch occupies its normal or reverse position, and a latch cooperating with said actuating members and effective upon relative displacement of said actuating members to retain the actuating members in their displaced relation to prevent at least one of said contact mechanisms from assuming one of its extreme positions.
28. In combination with a railway switch and operating mechanism for said switch comprising a driving member movable between two extreme positions for actuating said switch to its extreme positions, a detector rod positioned in accordance with the position of said switch, two contact mechanisms each having normal and reverse positions, two actuating members each controlled by said detector rod and by said driving member and normally moving in unison, means controlled by each actuating member for separately driving a different one of said contact mechanisms to its normal or reverse position according as the switch occupies its normal or reverse position, and a latch cooperating with said actuating members and effective upon movement of said detector rod without movement of said driving member to lock the actuating mechanism in an abnormal relation in which at least one of said contact mechanisms is prevented from assuming its extreme position for either extreme position of the switch.
29. In combination with a railway switch and operating mechanism for said switch comprising a driving member movable between two extreme positions for actuating said switch to its extreme positions, a motion plate operatively connected with said driving member to move therewith, a detector rod positioned in accordance with the position of the switch, two contact mechanisms each having normal and reverse positions, two rockshafts each controlled by said motion plate and said detector rod and normally moving in unison, means controlled by each rockshaft for separately driving a different one of said contact mechanisms to its normal or reverse position according as the switch occupies its normal or reverse position, and a latch cooperating with said rockshafts and effective upon relative displacement of said rockshafts to retain said rockshafts in their displaced relation to prevent at least one of said contact mechanisms from assuming one of its extreme positions.
30. In combination with a railway switch and operating mechanism for said switch comprising a driving member movable between two extreme positions for actuating said switch to its extreme positions, a detector rod positioned in accordance with the position of said switch, two contact mechanisms each having normal and reverse positions, two actuating members each controlled by said detector rod and by said driving member and normally moving in unison, and means controlled by each actuating member for separately driving a different one of said contact mechanisms to its normal or reverse position according as the switch occupies its normal or reverse position.
31. In combination with a railway switch and operating mechanism for said switch comprising a driving member movable between two extreme positions for actuating said switch to its extreme positions, a motion plate operatively connected with said driving member to move therewith, a detector rod positioned in accordance with the position of the switch, two contact mechanisms each having normal and reverse positions, two rockshafts each controlled by said motion plate and said detector rod and normally moving in unison, and means controlled by each rockshaft for separately driving a different one of said contact mechanisms to its normal or reverse position according as the switch occupies its normal or reverse position.
32. In combination with a railway switch and operating mechanism for said switch comprising a driving member movable between two extreme positions for actuating said switch to its extreme positions, a motion plate operatively connected with said driving member to move therewith, a detector rod positioned in accordance with the position of the switch, two contact mechanisms each having normal and reverse positions, two rockshafts each controlled by said motion plate and said detector rod and normally moving in unison, means controlled by each rockshaft for separately driving a different one of said contact mechanisms to its normal or reverse position according as the switch occupies its normal or reverse position, and a latch cooperating with said rockshafts and effective upon movement of said detector rod without movement of said driving members to lock the rockshafts in an abnormal relation in which at least one of said contact mechanisms is prevented from assuming its extreme position for either extreme position of the switch.
33. In combination with a railway switch, a slide bar movable longitudinally between normal and reverse positions and operatively connected with the switch in such manner that movement of said slide bar from its normal position to its reverse position first unlocks the switch points,

then reverses them, and finally relocks the switch points in their reverse positions, and vice versa; two rockshafts, means controlled in part by said slide bar for normally rotating said rockshafts in

- 5 unison to one extreme position, to another extreme position, or to an intermediate position according as said slide bar occupies its normal position, its reverse position, or any position intermediate these two positions, two rotatable contact drums one controlled by each rockshaft and each arranged to be rotated to a normal extreme position, an intermediate position, or a reverse extreme position according as the associated rockshaft is rotated to its one extreme
  - 10 position, its intermediate position, or its other extreme position, a point detector rod positioned according to the position of the switch points, and means controlled by said point detector rod for rotating said rockshafts relative to each other
  - 15 if a train trails the switch when the switch occupies either extreme position.
  - 20

34. In combination with a railway switch, a slide bar movable longitudinally between normal and reverse positions and operatively connected with the switch in such manner that movement of said slide bar from its normal position to its reverse position first unlocks the switch points, then reverses them, and finally relocks the switch points in their reverse positions, and vice versa,

25 30 two rockshafts, means controlled in part by said slide bar for normally rotating said rockshafts in unison to one extreme position, to another extreme position, or to an intermediate position according as said slide bar occupies its normal position, its reverse position, or any position intermediate these two positions, two rotatable contact drums one controlled by each rockshaft and each arranged to be rotated to a normal extreme position, an intermediate position, or a

35 40 reverse extreme position according as the associated rockshaft is rotated to its one extreme position, its intermediate position, or its other extreme position, a point detector rod positioned according to the position of the switch points,

45 50 means controlled by said point detector rod for rotating said rockshafts relative to each other if a train trails the switch when the switch occupies either extreme position, and a latch operatively connected with said rockshafts and effective upon relative displacement of said rockshafts to retain the rockshafts in their displaced relation to prevent at least one of said contact drums from assuming one of its extreme positions.

35. In combination with a railway switch, a
55 slide bar movable longitudinally between normal
and reverse positions and operatively connected
with the switch in such manner that movement
of said slide bar from its normal position to its
reverse position first unlocks the switch points,
60 then reverses them, and finally relocks the switch
points in their reverse positions, and vice versa,
two rockshafts, means controlled in part by said
slide bar for normally rotating said rockshafts in
unison to one extreme position, to another ex-
65 treme position, or to an intermediate position
according as said slide bar occupies its normal
position, its reverse position, or any position in-
termediate these two positions, two rotatable
66 contact drums one controlled by each rockshaft
and each arranged to be rotated to a normal ex-
treme position, an intermediate position, or a
reverse extreme position according as the asso-
ciated rockshaft is rotated to its one extreme po-
sition, its intermediate position, or its other ex-
70 treme position, a point detector rod positioned
75

according to the position of the switch points, means controlled by said point detector rod for rotating said rockshafts relative to each other if a train trails the switch when the switch occupies either extreme position, normal indication contacts controlled by the one drum and arranged to be closed when and only when said one drum occupies its normal extreme position, reverse indication contacts controlled by the other drum and arranged to be closed when and only when 10 said other drum occupies its reverse extreme position, and shunting contacts one controlled by each drum and each arranged to be closed when and only when the associated drum occupies its intermediate position. 15

36. In combination with a railway switch, a slide bar movable longitudinally between normal and reverse positions and operatively connected with the switch in such manner that movement of said slide bar from its normal position to its reverse position first unlocks the switch points, then reverses them, and finally relocks the switch points in their reverse positions, and vice versa, two rockshafts, means controlled in part by said slide bar for normally rotating said rockshafts in unison to one extreme position, to another extreme position, or to an intermediate position according as said slide bar occupies its normal position, its reverse position, or any position intermediate these two positions, two rotatable contact drums one controlled by each rockshaft and each arranged to be rotated to a normal extreme position, an intermediate position, or a reverse extreme position according as the associated rockshaft is rotated to its one extreme position, its intermediate position, or its other extreme position, a point detector rod positioned according to the position of the switch points, means controlled by said point detector rod for rotating said rockshafts relative to each other if a train trails the switch when the switch occupies either extreme position, normal indication contacts controlled by the one drum and arranged to be closed when and only when said one drum occupies its normal extreme position, reverse indication contacts controlled by the other drum and arranged to be closed when and only when said other drum occupies its reverse extreme position, shunting contacts one controlled by each drum and each arranged to be closed when and only when the associated drum occupies its intermediate position, and a latch operatively connected with said rockshafts and effective upon relative displacement of said rockshafts to retain the rockshafts in their displaced relation to prevent at least one of said contact drums from assuming one of its extreme positions.

37. In combination with a railway switch, a slide bar movable longitudinally between normal and reverse positions and operatively connected with the switch for moving the switch between its normal and reverse positions, two rockshafts journaled on opposite sides of said slide bar, a first crank arm secured to the one rockshaft and provided with a first roller, a second crank arm secured to the other rockshaft and provided with a second roller, a motion plate secured to said slide bar and cooperating at its opposite edges with said first and second rollers respectively, the one edge of said motion plate being provided with a first recess which aligns with said first roller when and only when the slide bar occupies its normal extreme position and with a second recess which is approximately half as deep as said first recess and which aligns with said first roller at

all times except when said slide bar occupies one or the other of its two extreme positions, the other edge of said motion plate being provided with a third recess which aligns with said second roller when and only when said slide bar occupies its reverse extreme position and with a fourth recess which is approximately half as deep as said third recess and which aligns with said second roller at all times except when said slide bar occupies one or the other of its extreme positions, a spring stretched between said first and second arms and constantly biasing said first and second arms to such positions that said first and second rollers will enter the associated recesses in the motion plate whenever the associated recesses in the motion plate are in the proper positions to receive these rollers, the recesses in the motion plate being so designed that movement of said rockshafts caused by cooperation of said roller with these recesses will be in unison, whereby said first and second rockshafts are normally each rotated to one extreme position, to another extreme position, or to an intermediate position according as said slide bar occupies its normal extreme position, its reverse extreme position, or any position intermediate these two positions, two rotatable contact drums one controlled by each rockshaft and each arranged to be rotated to a normal extreme position, an intermediate position, or a reverse extreme position according as the associated rockshaft is rotated to its one extreme position, its intermediate position, or its other extreme position, a point detector rod positioned according to the position of the switch points, and means controlled by said point detector rod for rotating said one rockshaft away from its one extreme position if a train trails the switch when the switch occupies its normal position and for rotating the other rockshaft away from its other extreme position if a train trails the switch when the switch occupies its reverse position.

38. In combination with a railway switch, a slide bar movable longitudinally between normal and reverse positions and operatively connected with the switch for moving the switch between its normal and reverse positions, two rockshafts journaled on opposite sides of said slide bar, a first crank arm secured to the one rockshaft and provided with a first roller, a second crank arm secured to the other rockshaft and provided with a second roller, a motion plate secured to said slide bar and cooperating at its opposite edges with said first and second rollers respectively, the one edge of said motion plate being provided with a first recess which aligns with said first roller when and only when the slide bar occupies its normal extreme position and with a second recess which is approximately half as deep as said first recess and which aligns with said first roller at all times except when said slide bar occupies one or the other of its two extreme positions, the other edge of said motion plate being provided with a third recess which aligns with said second roller when and only when said slide bar occupies its reverse extreme position and with a fourth recess which is approximately half as deep as said third recess and which aligns with said second roller at all times except when said slide bar occupies one or the other of its extreme positions, a spring stretched between said first and second arms and constantly biasing said first and second arms to such positions that said first and second rollers will enter the associated recesses in the motion plate whenever the associated recesses in the motion plate are in the proper positions to receive these rollers, the recesses in the motion plate being so designed that movement of said rockshafts caused by cooperation of said roller with these recesses will be in unison, whereby said first and second rockshafts are normally each rotated to one extreme position, to another extreme position, or to an intermediate position according as said slide bar occupies its normal extreme position, its reverse extreme position, or any position intermediate these two positions, two rotatable contact drums one controlled by each rockshaft and each arranged to be rotated to a normal extreme position, an intermediate position, or a reverse extreme position according as the associated rockshaft is rotated to its one extreme position, its intermediate position, or its other extreme position, a point detector rod positioned according to the position of the switch being so designed that movement of said rock-

shafts caused by cooperation of said roller with these recesses will be in unison, whereby said first and second rockshafts are normally each rotated to one extreme position, to another extreme position, or to an intermediate position according as said slide bar occupies its normal extreme position, its reverse extreme position, or any position intermediate these two positions, two rotatable contact drums one controlled by each rockshaft and each arranged to be rotated to a normal extreme position, an intermediate position, or a reverse extreme position according as the associated rockshaft is rotated to its one extreme position, its intermediate position, or its other extreme position, a point detector rod positioned according to the position of the switch points, and means controlled by said point detector rod for rotating said one rockshaft away from its one extreme position if a train trails the switch when the switch occupies its normal position and for rotating the other rockshaft away from its other extreme position if a train trails the switch when the switch occupies its reverse position.

39. In combination with a railway switch, a slide bar movable longitudinally between normal and reverse positions and operatively connected with the switch for moving the switch between its normal and reverse positions, two rockshafts journaled on opposite sides of said slide bar, a first crank arm secured to the one rockshaft and provided with a first roller, a second crank arm secured to the other rockshaft and provided with a second roller, a motion plate secured to said slide bar and cooperating at its opposite edges with said first and second rollers respectively, the one edge of said motion plate being provided with a first recess which aligns with said first roller when and only when the slide bar occupies its normal extreme position and with a second recess which is approximately half as deep as said first recess and which aligns with said first roller at all times except when said slide bar occupies one or the other of its two extreme positions, the other edge of said motion plate being provided with a third recess which aligns with said second roller when and only when said slide bar occupies its reverse extreme position and with a fourth recess which is approximately half as deep as said third recess and which aligns with said second roller at all times except when said slide bar occupies one or the other of its extreme positions, a spring stretched between said first and second arms and constantly biasing said first and second arms to such positions that said first and second rollers will enter the associated recesses in the motion plate whenever the associated recesses in the motion plate are in the proper positions to receive these rollers, the recesses in the motion plate being so designed that movement of said rockshafts caused by cooperation of said roller with these recesses will be in unison, whereby said first and second rockshafts are normally each rotated to one extreme position, to another extreme position, or to an intermediate position according as said slide bar occupies its normal extreme position, its reverse extreme position, or any position intermediate these two positions, two rotatable contact drums one controlled by each rockshaft and each arranged to be rotated to a normal extreme position, an intermediate position, or a reverse extreme position according as the associated rockshaft is rotated to its one extreme position, its intermediate position, or its other extreme position, a point detector rod positioned according to the position of the switch 75

position according as said driving member is moved to its normal position, to its reverse position, or to any position intermediate its normal and reverse positions, a point detector rod positioned in accordance with the position of said switch, means controlled by said detector rod for rotating said first rockshaft to its intermediate position if the switch points are displaced from their normal extreme positions when said 5 driving member occupies its normal position, other means controlled by said point detector rod for rotating said second rockshaft to its intermediate position if the switch points are displaced from their reverse extreme positions when 10 15 20 25 30 35 40 45 50 55 60 65 70 75 said driving member occupies its reverse position, two contact mechanisms one operatively connected with each rockshaft in such manner that each contact mechanism will be moved to a normal position, an intermediate position or a reverse position according as the associated rockshaft is rotated to its one extreme position, its intermediate position, or its other extreme position, first and second crank arms secured to said first and second rockshafts respectively in such manner that when said rockshafts are rotated in unison the spacing between the arms will remain constant, but that, if either rockshaft is moved toward its intermediate position without the other rockshaft being simultaneously moved toward its intermediate position the spacing between said arms will be increased, a latching plunger mounted on one arm and biased to an upper position, a latch rod pivotally attached at one end to the other arm and provided at its free end with a latch head which cooperates with said latching plunger, the parts being so proportioned that when said arms are in their normal relative positions said latch head will overlie said latching plunger and prevent said latching plunger from rising due to its bias but that when the spacing between said arms is increased said latch head will release said latching plunger and permit it to rise to its upper position in which it engages said latch head in such manner that said arms are prevented from returning to their normal relative positions until 20 25 30 35 40 45 50 55 60 65 70 75 said latching plunger is manually depressed.

45. In a circuit controller, in combination, two contact mechanisms each movable between an intermediate and two extreme positions, separate actuating mechanisms for said contact mechanisms, said actuating mechanisms normally moving in unison and each including an arm which when said mechanisms move in unison remains in a fixed spaced relation with respect to the other arm, the one arm being provided with a hole extending therethrough and with a lug having a portion extending parallel to the arm a spaced distance above one end of said hole, said lug also being provided with a hole, a tube closed at one end and having the other end secured to said one arm and extending into the other end of the hole in said one arm, a latching plunger mounted to slide within said tube and the hole in said one arm and provided at its upper end with a portion of reduced diameter which cooperates with the hole in said lug to guide the movement of said plunger in said tube, a spring in said tube which biases said plunger to an upper position, a latch rod pivotally connected at one end to said other arm, a latch head adjustably secured to the free end of said latch rod and disposed to slide between said lug and said one arm and provided with an axially extending slot which slidably receives the upper end portion of said latching plunger, said latch head also being provided with a concave surface which slopes downwardly from the inner end of said slot toward said one arm and which has a radius of curvature which is only a little larger than the radius of curvature of said latching plunger, the parts being so proportioned that when said arms occupy said fixed spaced relation the surface of said latch head adjacent the lower end of said concave surface will overlie the upper surface of the main part of said latching plunger and hold said latching plunger in a depressed position but that if said arms are moved relative to each other the lower surface of said latch head will move out of engagement with the upper surface of said latching plunger and permit said latching plunger to rise to a position in which the latching plunger engages the latch head at some point on said sloping concave surface, whereby when said arms are displaced relative to each other they will be subsequently held in their dis-

placed relation until said latching plunger is manually depressed.

46. In combination with a railway switch and operating mechanism for said switch including a member movable between two extreme positions for actuating said switch to its two extreme positions, a motion plate operatively connected with said member to move therewith, a rockshaft, means for operatively connecting said rockshaft with said motion plate in such manner that said rockshaft will be biased to one extreme position when said member occupies its one extreme position and will be positively moved to another extreme position when said member is moved to its other extreme position, a point detector rod secured to the switch to move therewith and provided with means which cooperates with means secured to said rockshaft for preventing said rockshaft from moving to its one extreme position when said driving member occupies said one extreme position unless said switch occupies its corresponding extreme position and the then closed point of said switch is in close engagement with the associated fixed rail, and indication means controlled by said rockshaft.

47. In combination with a railway switch and operating mechanism for said switch including a member movable between two extreme positions for actuating said switch to its two extreme positions, a motion plate operatively connected with said member to move therewith, a rockshaft, means for operatively connecting said rockshaft with said motion plate in such manner that said rockshaft will be biased to one extreme position when said member occupies its one extreme position and will be positively moved to another extreme position when said member is

5 moved to its other extreme position, a point detector rod secured to the switch to move therewith and provided with means which cooperates with means secured to said rockshaft for preventing said rockshaft from moving to its one extreme position when said driving member occupies said one extreme position unless said switch occupies its corresponding extreme position and the then closed point of said switch is in close engagement with the associated fixed rail, and 10 circuit controlling contacts controlled by said rockshaft.

48. In combination with a railway switch and operating mechanism for said switch including a member movable between two extreme positions 15 for actuating said switch to its two extreme positions, a motion plate operatively connected with said member to move therewith, a rockshaft, means for operatively connecting said rockshaft with said motion plate in such manner that said 20 rockshaft will be biased to one extreme position when said member occupies its one extreme position and will be positively moved to another extreme position when said member is moved to its other extreme position, a roller secured to 25 said rockshaft, a point detector rod secured to said switch to move therewith and provided with a notch which aligns with said roller when and only when the switch occupies the extreme position corresponding to said one extreme position 30 of said member, the parts being so proportioned that said rockshaft will be prevented from moving to its one extreme position except when said notch aligns with said roller, and indication means controlled by said rockshaft. 35

HERBERT L. BONE.
